ERNST BREITLING, WILHELM BRAUER, AND KARL AUGUST LEHMANN, OF ESSEN, GERMANY, AND BRUNO BORNKESSEL, DECEASED, LATE OF ESSEN, GERMANY, BY MARTHA BORNKESSEL, OF ESSEN-ON-THE-RUHR, GERMANY, ADMINISTRATRIX; SAID BREITLING, BRAUER, LEHMANN AND BRUNO BORNKESSEL ASSIGNEES TO FRIED KRUPP AKTIENGESELLSCHAFT, OF ESSEN-ON-THE-RUHR, GERMANY

BOOKKEEPING MACHINE

Original application filed February 24, 1925, Serial No. 11,373, and in Germany February 25, 1924. Divided and this application filed September 30, 1927. Serial No. 223,196.

Key locking mechanism for book keeping machines

The invention relates to a book keeping machine for calculating and recording a new state of an amount consisting of an old state of an account and the amounts received and paid out, and in particular to a machine of the character stated in which the amounts and the operations to be executed by the machine are set by means of keys and are transmitted by a separate drive to the totalizers and to the printing and display mechanism.

The spirit of the invention consists in the general common idea of providing devices which serve for easing the operator's effort of thought in the largest possible degree and to warrant a reliable control of the transaction both for the office and for the customer.

For this purpose the different transactions including an action upon the control totalizers and the display mechanism and record on different impression carriers, are set by as few manipulations as possible, the succession of the setting manipulations required for the different transactions being prescribed to the operator by the machine in a manner precluding error by means of locking mechanisms arranged between the several setting means.

With these and incidental objects in view, the invention consists in certain novel features of construction and combinations of parts, the essential elements of which are set forth in appended claims, and a preferred form of embodiment of which is hereinafter described with reference to the drawings which accompany and form part of the specification.

In these drawings:

Figs. 14 to 31 are sections parallel to the rows of keys of Fig. 7, all seen from the right,

Fig. 32 is the elevation of an item counter frame,

Fig. 33 is a detail thereto.

This invention relates more particularly to matter divided from our copending application Serial No. 11,373, filed February 24, 1925, for a book keeping machine. This book keeping machine is designed to take up the money transactions between an unlimited number of customers and a savings bank or bank. Each customer possesses an account number and the transactions in his account may take place by directly paying in or taking away amounts or by orders. For recording the transactions and the state of the account a continually impressed card and a continuously impressed book are made use of, the card remaining in the office and the book remaining in the customer's hand. The book must be presented in the office for recording the amounts in consideration. In case this is impossible, for instance with orders, the record must be made on a later occasion.

For controlling the transactions serves, besides, a control strip on which all the operations necessary for this control of the machine are recorded. The machine further hands, upon each transaction, a ticket to the customer whereon all the operations of the transaction are recorded. For the direct control of the set amount there is provided a dis-

play mechanism which may be read off both from the front and rear side of the machine.

One of the totalizers of the machine, the main totalizer, is destined for calculating a new state of account consisting of an old state and of the amounts received or paid out. Another totalizer, i. e. the auxiliary totalizer serves for calculating the arithmetic total from the amounts received and paid out in the different accounts of a determined booking period. Other totalizers, i. e. the transaction totalizers serve for controlling the single operations of the main totalizer, while still in further totalizers the amounts paid out and received of certain lines of business are added.

For setting the different operations of the machine keys are made use of exclusively, some of said keys causing a plurality of operations to be executed simultaneously. These keys are connected by blocking means controlling the mode of each setting operation and the mutual conditions of the different transactions. Owing to these arrangements setting operations cannot be omitted in a transaction, as the machine cannot be started before all required setting operations have been made. A certain number of the keys are connected, for control purposes, with item counters. Each transaction to be executed by the machine, the total-taking included, requires an operation of the machine initiated by depressing a motor key. The machine is driven by an electric motor.

35 1. General arrangement of the book keeping machine

The setting mechanism of the machine (Fig. 1) consists of the amount keys 10, arranged in the nine rows at the left-hand front part of the machine, of two rows of special keys 11 and 12, three rows of account totalizer keys 13 and of the motor key 14 at the right-hand front part of the machine. To the keys 13 are allotted the item totalizers 15 and to the six upper keys of the key row 11 are allotted item totalizers 16. The lower front part of the machine is occupied by the printing mechanism arranged across the machine (Figs 1 and 4), said mechanism showing at its upper side seven rows of keys 17 serving for setting the account number wheels. The key 18 is a general releasing key for the keys 17. In the upper part of the machine is arranged the display mechanism which may be read-off both from the front and rear side of the machine.

The left-hand part of the inner space of the machine is occupied by the amount differential mechanism and the totalizers, see Fig. 2. To the totalizers belong: twenty-seven account totalizers which are superimposed so as to form three groups N_1 , N_2 , N_3 of nine totalizers each (Fig. 2) further: six transaction totalizers united so as to form a

group S, an auxiliary totalizer HR arranged below said last-named group S and a main totalizer R. The main and auxiliary totalizer are destined for additions and subtractions while the other totalizers are adapted to be used for additions only. As will be seen from Fig. 2, each two groups of totalizers are supported on three blocks 19, 20, 21, the latter being fixed on parts of the frame 23 of the machine by means of screw bolts 22.

The right-hand part of the interior of the machine is taken by the controlling devices for the totalizers, the blocking means for the special keys and by the driving mechanism.

80 2. The modes of record

Four different modes of record are capable of being executed by the machine:

I. The ordinary record (record of first order);

II. Recording the sub-total from the main totalizer (record of second order);

III. Recording sub-totals and grand-totals from the controlling totalizers (record of third order);

IV. Recording addenda (record of fourth order).

I. An ordinary record required three different modes of operations of the machine viz: introduction of the old state of account, introduction of the amounts received or paid out, printing the new state of account. The introduction of the old state and the impression of the new state each requires an operation of the machine, while in introducing the amounts received and paid out a separate operation is required for recording each amount received or paid out.

The mode of operation of the main totalizer and the simultaneous throwing-in of a controlling totalizer of the group S (Fig. 2) is caused by the six upper keys $-B$, $+B$, Ab , Zu , $-b + b$ (Fig. 1) of the row 11, said keys being denoted hereinafter the main keys. The by-keys 13 are able to be depressed upon introducing amounts received and paid out only. When this takes place they cause an account totalizer to be thrown in also, to which the amount received or paid out is transmitted additively. The account totalizers are subdivided into two groups, the group influenced by the by-keys 1 to 9 and 19 to 23 being allotted to the amounts received and the group influenced by the by-keys 10 to 18 and 24 to 27 to the amounts paid out.

In order to introduce the old state in the machine, after depressing the corresponding amount keys 10 and account keys 17 one of the keys $-B$ and $+B$ is depressed and, namely, the key $+B$ if it is a matter of a positive value, and the key $-B$ if it is a matter of a negative one. Hereby the motor key M is released and the operation of the ma-

chine is started by depressing this key, the set amount thus being transmitted to the main totalizer, the corresponding transaction totalizer $-B$ or $+B$ and to the printing and display mechanism. A transmission of the set amount to the auxiliary totalizer does not take place even in case the key **HR** is being depressed.

In order to introduce amounts received or paid out, after setting this amount by means of the amount keys 10, the by-key 13 determining the kind of said amount, the motor key **M** is released by depressing the main keys **Zu** or **Ab**, respectively. During the operation of the machine caused by the motor key **M**, the set amount is transmitted additively or subtractively to the main totalizer and additively to the transaction totalizer **Zu** or **Ab**, to the account totalizer thrown into operation and to the printing and display mechanism. In case the key **HR** is being depressed, then at the same time the additive or subtractive transmission to the auxiliary totalizer takes place.

25 This operation of the machine may be followed by any required member of operations recording amounts received or paid out.

With the third mode of operation the total contained in the main totalizer is taken. 30 According to whether the total is a positive or a negative one, the main key $-b$ or $+b$ is locked. There are further provided means causing one of the keys $-b$ or $+b$ to be able to be depressed only if no amount key is being set. By depressing the key $-b$ or $+b$ the motor key **M** is released. During the operation now following the main totalizer is zeroized and the total contained therein is transmitted additively to the corresponding 40 transaction totalizer $-b$ or $+b$ and the printing and display mechanism is positioned. A transmission to the auxiliary totalizer does not take place even in case the key **HR** is being depressed.

45 While the amount keys 10, the main keys, the key **RZ** and the keys **ZS**, **ES** are released at the end of each operation of the machine, the keys **HR** (auxiliary totalizer) and **N** (addenda) permanently remain set. They 50 are released by the keys **L** disposed below and above them, respectively. The account keys 17 set on the beginning of an ordinary transaction are released only at the end thereof, viz., after the new state of account has been 55 printed.

II. As the main totalizer is zeroized at the end of any ordinary transaction, a sub-total is able to be taken from the main totalizer only after an amount received or paid out has 60 been recorded. By depressing the key **RZ** (sub-total of the main totalizer) the motor key **M** is released, such depressing being possible only if no amount key 10 being depressed. Upon starting the machine, the transmission 65 of the sub-total from the main totalizer onto

the printing and display mechanism takes place. In case this sub-total is a negative one, the machine adjusts itself automatically in the described manner for taking negative totals.

70 III. If from one of the six transaction totalizers $-B$, $+B$, **Ab**, **Zu**, $-b$, $+b$, from the auxiliary totalizer or from one of the account totalizers the total is to be taken, one of the keys **ZS** (sub-totals) or **ES** (grand totals) is first depressed, this being possible only if none of the amount keys is being depressed. By depressing the keys **ES** and **ZS**, the keys **HR** and the by-keys 13 which generally do not cause the release of the motor key **M**, become releasing keys for the motor key as this is permanently the case with the main keys. If now one of the main keys is depressed, or one of the by-keys or the key **HR**, the motor key **M** is released. With the 80 operation started by said key **M**, the sub-total or grand total is taken from the totalizer selected by depressing said main or by-key or the key **HR**.

IV. The key **N** (addenda) has to be depressed in case ordinary transactions are to be recorded as addenda, as hereinafter described in detail. With the addendum key **N** depressed, all the totalizers are thrown out of operation except the main totalizer. The 95 record of an ordinary transaction is therefore effected by the main totalizer although the main and by-keys are thrown-in when this takes place.

The depression of the addendum key **N** 100 besides causes certain special operations to be effected, as hereinafter described. As to the rest, the mode of function of the machine is the same as in an ordinary transaction.

3. The setting mechanisms

Each row of the shafts 25 of the keys 10 (Figs. 2 and 4) has mounted beside it on rolls 26, 27 two bars, namely a locking bar 28 (Fig. 2) and a block bar 29 (Fig. 4), said bars 110 cooperating with pins 30 mounted on the key shafts 25. Within the range of each key pin 30 the locking bar has a hook-shaped part 31 and normally takes, under the action of a spring 33, its lower end position in which it abuts against the guiding roll 26. The keys are mounted for horizontal shifting motion in a key board 34 and in bent-off portions of partitions 36. Springs 37 wound on their shafts will keep them in their left-hand end position.

Upon depressing one of the keys 10 the bar 28 is pushed upwardly by the pin 30 engaging the oblique face of the hook-shaped portion and will rush downwardly as soon as the pin 30 has passed the point of the hook, thereby engaging with its hook-shaped portion 31 over the pin 30 and fixing the key in its setting position. In case another key 10 has been 125 depressed in the same row, this latter key is 130

released in the well-known manner with the upward motion of the bar 28.

A bow 39 is mounted on a fixed shaft 38 and is guided along prolongations 40 of the bars 28. This bow 39 carries on one side a roll 41 which is pressed by a spring against a cam disk 43 fixed on the shaft 42. This shaft 42 executes a revolution in anti-clockwise direction upon each operation of the machine. At the end of this revolution the cam of the disk 43 will engage the roll 41 and rock the bow 39 in clockwise direction, whereby all of the locking bars undergo an upward motion causing the release of the set keys. In order to release the set keys by hand, a general releasing key 44 is to be depressed (Fig. 1) which imparts to the bow 39 the rocking motion in clockwise direction required for the upward motion of the bar 28 in a manner not shown. Another bow 46 likewise mounted on the shaft 38 and provided with a roll 45 abuts against a cam disk 47 fixed on the shaft 42 under the action of a spring. Upon rotating the cam disk 47 the cross portion of the bow 46 engages over the hook-shaped lugs 48 of the bars 28 and keeps the latter in their lower end positions so that all of the keys are locked in their positions.

Above the roll 27 there is mounted in the frame of the machine a shaft 49 (Figs. 2 and 3) to which are rigidly connected arms 55 projecting into the range of the upper prolongations 50 of the bars 28. The shaft 49 is able to be rocked by the action of certain special keys, whereby the arms 55 engage over the prolongations 50 and cause a locking of the keys, like the bow 46.

The block bar 29, Fig. 4, shiftably mounted beside the bar 28 on the rolls 26, 27 shows V-shaped recesses the oblique faces 56 of which cooperate with the key pins 30. A pin 58 of a lever 59 pivoted on the partition 36 engages a slot 57, Fig. 2, in block bar 29, the other end of said lever abutting against a pin 60 of a zero locking lever 62. This lever is pivoted on a shaft 61 and is acted upon in clockwise direction by a spring 51, see Fig. 3. A notch 63 of this lever 62 normally projects into the path of a pin 64 which is fixed on the differential member 65 belonging to the key row in question, said lever 62 locking the member 65 in zero position. A spring 66 attached between the frame of the machine and the lever 59 normally keeps the block bar 29 in its lower end position. Upon depressing a key the block bar 29 will be upwardly shifted by the pin 30 engaging the oblique face 56, whereby an anti-clockwise rocking motion is imparted to the zero locking lever 62 which thus releases the differential member in consideration.

In order to release, with taking totals, all the members 65 before the beginning of the differential operation, there is mounted on the shaft 61 a bow 67 which engages behind

lower prolongations 52 of the zero locking levers 62 and moves the notches 63 of said levers 62 out of the path of the pins 64 by an anti-clockwise rocking motion taking place with a rotation of the shaft 61.

The special differential mechanism (Fig. 5) is of a construction similar to that of the amount differential mechanism. It cooperates with the totalizer controlling mechanism and the printing mechanism. In correspondence with the five rows of keys 11, 13, 12 (Fig. 1) the special differential mechanism shows five groups of differential elements. The differential member allotted to the keys 11 is denoted by 251 (Fig. 5), that allotted to the keys 13 by 253, and that allotted to the keys 12 by 252. The differential members carrying pins 64 cooperating with zero pawls 62' influenced by springs 51' whereby said members are held in their position at rest as long as no key of the row in question is being depressed. Among the keys 12 only those denoted by N, ZS and ES cooperate with the differential member 252, so that the differential member 252 is able to assume, besides the zero position, still three other differential positions only. The keys L and M are without influence on the pawls 62' of this row of keys. The same is the case as to the key L of the row of keys 11 to the differential member 251. The detent and releasing means of the special setting mechanism is described below. In the setting mechanism for the account members each account key 17 cooperates by means of a pin 590 (Fig. 4) with block- and locking-bars 591, 592 arranged on the side of the row of keys in consideration. These bars are designed like the bars 28, 29 (Fig. 4) of the amount setting mechanism. The stems 589 of the keys 17 control the positioning of differential shafts 587 connected with the type wheels for the account numbers.

4. The key blocking means

Blocking means are provided between the keys 10, 11, 12, 13, 17 and M (Fig. 1) compelling the operator to make all the setting operations belonging to a transaction, before the operation of the machine is released and preventing him from making other setting operations than those belonging to this transaction. These means further cause the different records of an ordinary transaction to be made in the prescribed succession only, they further effect that during an ordinary transaction only the records of second and fourth order can be made and that amounts to be set and occurring again in succeeding records of the machine, need to be set one time only.

The whole means serving for the above-mentioned purposes are of the following four kinds: Means for releasing the keys, means for mutually blocking the keys, means for determining the setting succession in one

operation of the machine and means for determining the setting succession of the different records of a transaction.

5. The key releasing means

The release of the amount keys 10, of the main keys, of the key RZ, of the by-keys 13, of the keys ZS, ES takes place at the end of each operation of the machine. All the above-named keys cooperate with locking bars which engage, in the manner described with the amount keys, by hook-shaped portions 31 (Fig. 2) over pins 30 of the depressed keys. To release the keys the locking bars are pushed upwardly by releasing bows, the key pins 30 being disengaged by the hook portions 31 of the said bars and the keys rushing back by spring action, into their position of rest. As to the amount keys, the releasing bow 39 rocking about the shaft 38 (Figs. 2, 12) effects the releasing motion of the locking bars 28 (Fig. 2) in the manner described in chapter 2.

The shaft 38 (Figs. 12, 5) extends to the right up to below the key boards of the transaction keys and has there loosely mounted on it a releasing bow 891 engaging by a roll 892 (Fig. 5) a cam disk 893 (Figs. 5, 12) fixed to the driving shaft 42. The bow 891 cooperates with lower prolongations 40 of a locking bar 901 (Fig. 23) for the keys -B to RZ of the row 11 and of locking bars 894 (Fig. 24), 895 (Fig. 25), 896 (Fig. 27) for the by-keys 13 and with a locking bar 898 (Fig. 30) for the keys ES, ZS. The disk 893 (Figs. 5, 12) is of a shape like that of the disk 43 (Fig. 2) so that the release of said amount and transaction keys takes place at the same time, at the end of each operation. As in the amount setting mechanism the said locking bars are guided by end slots on rolls and bars 26, 27. Springs 899 (Figs. 24, 27) cause them to yieldingly abut on said rolls and bars.

The release of the keys HR and N does not take place by means of the driving mechanism, but by means of special releasing keys L. The keys HR and L of the row 11 cooperate with a locking bar 900 (Fig. 21) acted upon by a spring 899. As this bar 900 does not show the lower prolongation 40, it is not influenced by the releasing bow 891. Upon the key HR being depressed, the bar 900 engages with its hook portion 56 over a bar 905 connected as hereinafter described to the key HR, and locks the same in its set position, until the key L is depressed. This key L cooperates, by a bar 905, with a tapered surface 907 of the locking bar 900 and takes the hook portion 56 out of the path of the bar 905 of the key HR, the latter thus rushing back into its position of rest. If the key L is left after the key HR has been released, it returns by spring action to its position of rest.

In a similar manner cooperate the keys N and L with a locking bar 908 (Fig. 30). The locking bars 591 (Figs. 4, 14) for the account keys cooperate, by prolongations 909, with a releasing bow 910 (Figs. 14, 13, 12) which is fastened on a shaft 911 supported on the key frame. The shaft 911 is capable of being shifted axially and is normally held by a spring 912 in its left-hand end position (Fig. 12). In this position an arm 913 of said shaft 911 so cooperates with an arm 914 (Figs. 12, 14) of the releasing bow 891 that on every releasing motion of said bow the bow 910 likewise receives a releasing motion and releases the set account keys 17.

As in an ordinary transaction the account number remains the same during the different operations of the machine, its release takes place, in order to obviate a repeated setting thereof, only at the end of the whole transaction viz. after the impression of the new state of account effected by depressing the keys +b, -b has been made. At the beginning of the first operation of a record of first order the frame formed by the shaft 911 and the bow 910 is laterally shifted by means hereinafter described, so that the arm 913 of the shaft 911 comes out of the path of the arm 914 of the bow 891 and a release of the account keys is prevented. Only after depressing one of the keys -b, +b the said frame is again brought back into its normal position by means hereinafter described whereby the arm 914 is capable of transmitting its releasing motion to the arm 913.

As described in chapter 3, amount keys 10 of one row can be released by depressing another key of the same row. This is the case also with the account keys 17. Wrongly depressed amount keys can be released before starting the operation of the machine, by the general releasing key 44 (Fig. 1), denoted by L, while wrongly depressed account keys 17 can be released by the general releasing key 18 (Fig. 1). The key 18 cooperates by its shaft 915 (Figs. 12, 13) with a prolongation 916 of the releasing bow 910.

6. The mutual blocking of the keys of a row

The rows of the transaction keys are provided with detent devices which cause generally one key only of a row to be able to be depressed. These detent devices are formed, in a well-known manner, by detent disks 917 (Fig. 23) which are mounted on two supports 918 (Figs. 7, 9) arranged on the left-hand side of the rows of keys, and cooperate with pins 902 of the shafts of the keys. The whole space between said disks 917 is so chosen that one of the pins 902 only is capable of entering between the disks so that a simultaneous depression of two or more keys is rendered impossible.

In the row of keys 11 said pins 902 are not fixed on the keys 11 themselves but on blind

keys 920 (Figs. 7, 9, 14) which are guided like the keys 11 in partitions 921 of the key frame and possess neither the hand nor cooperate by their feet with differential members of the transaction totalizer.

The blind keys 920 are connected to the keys 11 by means of a frame which is formed by a bow 922 (Figs. 7, 14) rotatably mounted by pins 923 (Fig. 14) on the partitions 921, and by the bar 905 rigidly connected to said bow. The bar 905 engages by both ends slots 925 of the keys 11 and of the blind keys 920, as illustrated with one blind key in Fig. 9. By the described connection the blind keys 920 are compelled to take part in all movements of the keys 11 so that the detent device 917, 918 arranged on the left-hand side of the blind keys is operative also for the keys 11.

As it will be seen from Figures 7 and 23, the keys HR and L of the row 11 are not subject to the detent action of the device 917, 918. As the key HR has to cause the auxiliary totalizer also to the thrown-in for desired number of transactions, this key must be able to be depressed together with another key 11. The detent disks are therefore arranged between the upper seven keys only.

As to the row 12, the detent device 917, 918 (Fig. 7) works between the keys N, ZS, ES so that if the key N is being depressed, no totals can be taken from the control totalizers and, if one of the total keys ZS, ES is being depressed, no addenda can be recorded.

7. Locking the keys during operation of the machine

By depressing the motor key M (Fig. 31) all the keys are locked, the circuit for the driving motor is closed and the operation of the machine is initiated.

The shaft 505 (Fig. 31) of the motor key M has mounted on it a pin 926 which engages a slot 927 of an arm 929 fixed on the bow 928. The bow 928 which is loosely mounted on the rod 483 extends to the left up to the right-hand side of the amount keys (Fig. 3) and shows there a downwardly directed arm 930 to which is articulated a thrust bar 931 (Figs. 3, 31) cooperating with the cam disk 47 of the locking bow 46 (Figs. 3 and 2) for the amount keys. The disk 47 is mounted for limited rotation on the shaft 42 by means of a slot 932 (Fig. 3) provided on its hub and of a pin 933 fixed in the shaft 42. Another pin 934 (Figs. 3, 31) arranged on the right-hand side of said disk 47 is able to cooperate with the end of the thrust bar 931. This bar is laterally held by a disk 935 fixed on the hub of the disk 47.

The bow 928 shows on its right-hand end (Fig. 5) an arm 936 corresponding to the arm 930 and having pivoted to it a thrust bar 937 (Figs. 12, 31). This latter cooperates with a pin 938 (Fig. 31) of a disk 939 formed like the disk 47 and mounted for limited rota-

tion on the shaft 42 by means of a slot and pin connection 940, 941 (Fig. 5). The bar 937 is laterally guided by means of a disk 942. A roll 943 (Figs. 31, 12) of a locking bow 944, for the transaction keys, loosely mounted on the shaft 38 cooperates with said disk 939. The bow 944 is acted upon in clockwise direction by a spring 945 (Figs. 5, 24) and is able to cooperate with lugs 946 of the locking bar 901 (Fig. 23) for the keys -B to RZ, of locking bar 900 (Fig. 21) for the key HR, of locking bars 894 (Fig. 24), 895 (Fig. 25) and 896 (Fig. 27) for the by-keys 13, and 898, 908 (Fig. 30) for the keys 12.

When the machine is in position of rest, the rolls 45 and 943 (Fig. 31) are located in the deep portions of the disks 47 and 939, whereby the lugs 48 (Fig. 2) and 946 (Figs. 24 to 27) and therewith the corresponding keys are being released by the locking bows 46 and 944.

If now the motor key M is depressed, the bow 928 (Fig. 31) rotates in clockwise direction, the thrust bars 931, 937 move forwards (Fig. 31) and impart a partial rotation to the disks 47, 939 in anti-clockwise direction so that the rolls 45, 943 come opposite the full circumferential portion of said disks, the locking bows 46, 944 engage the lugs 48 (Fig. 2), 946 (Fig. 24) of the locking bars and all the amount and transaction keys are locked in their set and rest positions, respectively.

During the operation of the machine the keys remain locked, as the shaft 42 upon its rotation takes along with it the disks 47, 939 by means of the pins 933 (Fig. 3) and 941 (Fig. 5) and the disks turn, during their rotation, their full portion to the rolls 45, 943.

At the end of the operation of the machine, shortly before the releasing motion of the releasing bows 39 (Fig. 2) and 891 (Fig. 30), the deep portion of the disks reaches below the rolls 45, 943 (Fig. 31). This portion is engaged by the rolls of the locking bows under the action of their springs so that the key locking bars are released.

As soon as the ascending section of the deep circumferential portion of the disks reaches the rolls, this being the case shortly before the revolution of the shaft 42 is completed and when the disks have reached their initial position, said disks are stopped.

The locking bars 591 (Fig. 14) of the account keys show lugs 947 which cooperate with a locking bow 950 mounted on the frame by means of arms 948 (Figs. 14, 12) and a shaft 949. The right-hand arm 948 shows a rearward prolongation 955 having a pin 956. On this pin rests one arm of an angle lever 958 loosely mounted on the shaft 957 (Figs. 12, 14).

The upper arm of said angle lever 958 abuts against a projection 959 of the locking bow 944 of the transaction keys. It is evident that upon each locking motion of the bow 944 the bow 950 is likewise turned into locking position by the angle lever 958 so

that also the account keys 17 are locked when the motor key M is depressed and the machine operates.

A two-armed lever 954 mounted on the shaft 38 further cooperates with the pin 956 (Fig. 14) of the bow 950 for the account keys, said lever 954 being influenced in the manner described hereinafter by the keys -B, +B and -b, +b for the purpose of keeping the account keys locked also during the periods of rest arising between the single operations of a record of first order. The right-hand arm 948 of the bow 950 shows a bent-portion 960 (Figs. 14, 13) on which abuts the upper 15 arm of an angle lever 962 mounted in the frame by a pin 961. The lower arm of said angle lever acts upon the right-hand arm (Fig. 12) of the releasing frame 910, 911 (Fig. 13). When the bow 950 (Fig. 14) is 20 rocked upwardly into locking position, the angle lever 962 effects the lateral shifting of the releasing frame 910, 911 (Fig. 13) against the action of the spring 912, the arm 913 (Fig. 12) of the shaft 911 coming out of 25 the path of the arm 914 of the releasing bow 891 for the transaction keys. The releasing frame 910, 911 therefore cannot be actuated as long as the account keys are being locked.

30 8. Arrangement of the block bars and block bows

The different mutual blocking operations of the keys are substantially caused by block bars arranged beside the keys, said bars cooperating with block bows mounted on the block shaft 49 (Figs. 2, 7) situated above the setting mechanism. The disposition of said bars is illustrated in Figures 9 and 7. The block bars are provided like the described 35 lock bars, at their extremity with slots by means of which they are guided on rolls and rods 26, 27 respectively. They yieldingly abut against the lower rolls and rods 26 respectively. On the one hand the block bars 40 cooperate with the keys pins 30, 902 of the keys 12 and 13 and, respectively, with the rods 905 (Fig. 9) of the keys 11 and, on the other hand, in the manner hereinafter described, with prolongations of the block bows 45 or with special barring means.

50 Referring to Fig. 9, on the left are arranged the item counters 16 for the main keys, then follows to the right the detent device 917, 918 cooperating with the pins 902 of the blind keys 920.

Nine block bars cooperate with the rod 55 905 arranged between the blind keys 920 and the keys 11, viz. the block bars 963 (Fig. 14), 964 (Fig. 15), 965 (Fig. 16), 966 (Fig. 17), 967 (Fig. 18), 968 (Fig. 19), 969 (Fig. 20), 900 (Fig. 21), 970 (Fig. 22), from which the bar 900 (Fig. 21) serves, as above described, for blocking and releasing the key HR. On the right-hand side (Fig. 9) of the key row 65 11 is arranged the bar 901 (Fig. 23) cooper-

ating in the above described manner with the key pins 30. On the left-hand side of the rows 13 are situated the item counters 15 and the detent devices 917, 918 cooperating with the pins 902 of the keys 13. Beside the left-hand row of keys 13 for recording amounts received, there is still arranged, besides the described locking bar 894 (Fig. 24) a block bar 971 (Fig. 24); in the row of keys 13 recording the amounts paid out, there is arranged, besides the described locking bar 895 (Fig. 25) a block bar 972 (Fig. 25). Beside the row of keys 13 recording amounts received and paid out are, arranged besides the described locking bar 896 (Fig. 27) two block bars 973 (Fig. 26) and 974 (Fig. 27). The first-named bar 973 cooperates with the pins 30 of the "received"-keys 19 to 23 and the bar 974 cooperates with the pins of the "paid-out"-by-keys 24 to 27.

The row of keys 12 has no item counter. On its left-hand side is the described detent device 917, 918 (Fig. 9) cooperating with the key pins 902, while on its right-hand side are arranged, besides the described two locking and releasing bars, viz. 898 (Fig. 30) for the keys ZS and ES and 908 for the key N (Fig. 30), a block bar 975 (Fig. 28) for said key N and a block bar 976 (Fig. 29) for the keys ZS, ES.

As will be seen from Fig. 11, five auxiliary slides 977 (Fig. 15), 978 (Fig. 16), 979 (Fig. 17), 980 (Fig. 19), 981 (Fig. 22) are arranged between the keys 11 and the blind keys 920, besides the block bars 963 to 970 and 900. These auxiliary slides are guided by means of upper and lower slots 982 and 983, respectively, on cross bars 984, 985. These bars are mounted in a box-shaped casing 986, the side walls 987, 988 of which (Figs. 11, 21) are suspended by arms 989, 990 from the rods 26, 27 which guide the block bars. Springs 993 yieldingly act in upward direction on the auxiliary slide 974 to 980, said springs being attached to the upper end of a cross bar 994. The slides are further laterally guided by rear extensions 995 (Fig. 17) projecting through corresponding slots of the casing 986.

In the front and rear wall of the casing 986 (Fig. 18) are shiftably guided three locking cones 996 (Figs. 11, 18), 997 (Figs. 11, 14), 998 (Figs. 11, 18). These cones show a frontal abutting surface 999 by which they cooperate each with two of the bars 905 of the main keys, and are pressed forward by springs 1000. This forward action is limited by pins 1005 fixed on said cones and abutting against the casing 986. By a bent-portion 1006 (Fig. 11) the cone 996 cooperates with a lug 1007 (Fig. 17) of the auxiliary slide 979. The cone 998 (Figs. 11, 18) shows a bent-portion 1008 cooperating with a lug 1009 (Fig. 19) of the auxiliary slide 980, A

bent-portion 1010 (Figs. 11, 14) of the cone 997 cooperates with a lug 1011 (Fig. 15) of the auxiliary slide 977.

5 The block bows (Figs. 7, 8) mounted on the shaft 49 are partly rigid, rotatable, or shiftable thereon, when rotatable, they rotate partly in one, partly in both directions.

9. *Mutually locking the keys -b and +b*

10 The shaft 49 has loosely mounted on its left-hand side (Figs. 7, 8) two bows 1012 and 1013 the left arms 1014, 1015 of which engage, by slots, pins 1016, 1017 (Figs. 7, 6) of two-armed levers 1018, 1019 (Fig. 6). These levers are pivoted on a pin 1020 of the frame and are in connection, by thrust bars 432, 433 (Fig. 4), with the angle levers 428, 429 cooperating with a differential disk 265' for 20 the main totalizer. This disk 265' is connected to a mechanism for embodying the sign of the total contained in the main totalizer and is set hereby in determined angular positions, as fully described in said copending application Serial No. 11,373. The disk 265' possesses notches in such an arrangement that at every time the one of the levers 428, 429 is freed and the other is locked. Springs 1021 (Figs. 7, 6) cause the arms 1014, 1015 to normally abut against a pin 1022 (Figs. 7, 8), the lugs 430, 431 (Fig. 4) of the angle levers 428, 429 being kept out of the recesses of the disk 265'.

35 The right-hand arms of the bows 1012, 1013 (Fig. 7) project with downwardly directed extensions 1023, 1024 (Figs. 7, 8) into the path of rear claws 1025 (Figs. 18, 19) provided on the upper ends of the block bars 967, 968. The latter show tapered surfaces 1026 (Fig. 18) and 1027 (Fig. 19) cooperating with the rods 905 for the keys +b, -b.

40 Upon depressing the key -b or +b, the corresponding bar 905 acts upon the tapered surface 1026 or 1027 and tends to lift the block bar 967 or 968, respectively. The latter engages, in its turn, the claw 1024 or 1025 respectively and tends to turn the bow 1012 and 1013, respectively, in anti-clockwise direction. According to whether a recess of the disk 265' is opposite to the lug 430 and 431, respectively, (Fig. 4) of the angle lever 428 and 429, respectively, or not, this rotation and therewith the depression of the key 45 in question can take place or not. In the position shown in Fig. 4, of the disk 265' which corresponds to a negative total contained in the main totalizer, the key -b is being released, the key +b, however, is being

50 locked by means of the members 430, 428, 432, 1018, 1016, 1012, 1023, 968. In case a positive total is contained in the main totalizer the disk 265' presents to the angle lever 428 a recess. In this case the key +b 55 is free and the key -b is being locked.

10. *Mutually locking the amount keys and total keys (-b, +b, RZ, ZS, ES)*

The block shaft 49 shows rigid arms 55 (Figs. 2, 3) cooperating with slots 1028 of the upper ends of the block bars 29 (Fig. 4) 70 for the amount keys, said bars having V-shaped recesses. Within the range of the transaction keys the block shaft 49 is provided with three rigid arms 1029, 1030, 1031 (Figs. 7, 8). The arm 1029 (Fig. 14) presents a tapered surface to the frontal claw 1032 of the forked upper end of the block bar 963. This bar has a tapered surface 1033 which cooperates with the bar 905 allotted to the key RZ. The arm 1030 is opposite the claw 1032 (Fig. 15) of the block bar 964 which cooperates by tapered surfaces 1034 and 1035 with the bars 905 allotted to the keys -b, +b. The third arm 1031 of the shaft 49 (Fig. 29) is opposite a bent-portion 75 1036 of the claw 1032 of the block bar 976. The latter shows tapered surfaces 1037, 1038 cooperating with the pins 30 of the keys ZS, ES.

If one of the amount keys 10 (Fig. 2) 90 is depressed, the corresponding bar 29 is shifted upward, the slot 1028 thereof embracing the corresponding arm 55 of the shaft 49 and locks this shaft. Herewith also the arms 1029, 1030 and 1031 (Fig. 7) 95 are fixed and the block bars 963 (Fig. 14), 964 (Fig. 15) and 976 (Fig. 29) cannot be lifted, that is to say, the total keys -b, +b, RZ, ZS, ES are locked. A total key therefore cannot be depressed before the amount keys have been released. Inversely, no amount key can be depressed when one of the total keys has been set. Upon depressing one of the above-named total keys, the arm 1029, 1030 or 1031 in question, of the shaft 49, is engaged by the claw 1032 of the lifted block bar 963 (Fig. 14), 964 (Fig. 15) or 976 (Fig. 29). When this takes place, the shaft 49 (Fig. 2) has imparted to it a 100 partial rotation in clockwise direction whereby the lower arms 55 reach over the frontal claw 50 (Fig. 2) of the block bar 29 for the amount keys and lock it against being lifted and therewith said keys 10 against being depressed.

11. *Releasing the transaction differential members*

Each key of a row of keys releases, when 120 depressed, the corresponding differential member which is, in the position of rest of the machine, locked in zero position.

In the amount setting mechanism the pins 64 (Fig. 2) of the differential members 65, 125 80 are released, as described in chapter 3, by the zero locking levers 62, the bar 29 being shifted upward upon depressing a key of the row in consideration, and the lever 62 having imparted to it, by means of the lever 59, 130

a rocking motion towards the left. As to the transaction differential mechanism, the pins 64' of the differential members 251 for the key row 11, pins 64' of the differential members 253 for the row 13 and pins 64' of the differential members 252 for the row 12 are released in a similar manner by the zero locking levers 62' (Figs. 9, 5).

For the row of keys 11 there is arranged, instead of the sub-lever 59 (Fig. 2) a bow 1039 (Fig. 9), which is loosely mounted on a bar 1040 connecting the walls 987, 988 of the casing. This bow 1039 engages behind lugs 1041, 1042, 1043, 1044 of the block bars 963 (Fig. 14), 964 (Fig. 15), 969 (Fig. 20) and 970 (Fig. 22). The right-hand arm 1045 (Fig. 9) of the bow 1039 is prolonged to the rear and cooperates with the pin 60' of the lever 62' for the differential member 251. The block bar 969 (Fig. 20) shows a tapered surface 1046 which is influenced by the bar 905 belonging to the key HR. A lever 1052 still cooperates with the lug 1043 of the bar 969 (Figs. 20, 9), the other end of which lever 1052 engages by a slot 1053 the pin 426 of the control disk 409 which serves for throwing in and out the auxiliary totalizer. The bar 970 (Fig. 22) shows six lugs 1047 which cooperate with the bars 905 for the six main keys. Upon depressing one of said six main keys, the corresponding bar 905 engages a lug 1047 of the bar 970 and lifts it, the lug 1047 taking with it the bow 1039, the arm 1045 of which moves the zero locking lever 62' for the differential member 251 of the keys 11 into releasing position. In the same manner the differential member 251 is released by depressing the key HR by means of the bar 969 (Fig. 20) and by depressing the key RZ by means of the bar 963 (Fig. 14).

The sub-levers 59' (Fig. 9) for the rows 13, mounted on pivots 1051 of the partitions 921, show lateral lugs 1048 which cooperate in the left-hand row with a lug 1049 (Figs. 9, 24) of the bar 971, in the middle row with a lug 1050 (Fig. 9) of the bar 972 and in the right-hand row with lugs 1055 (Figs. 9, 26) and 1056 (Figs. 9, 27) of the bars 973 and 974. The bars 971 (Fig. 24) and 972 (Fig. 25) are provided with lugs 1057 for all the keys of the row belonging to it. The bar 973 (Fig. 26) shows only lugs 1057 for the five upper keys 19 to 23, the bar 974 (Fig. 27) shows lugs for the four lower keys 24 to 27. The zero locking lever 62' (Fig. 9) for the row 12 is provided, instead of with a pin 60' with a pin 1058 acted upon on one side by a sub-lever 1059 (Figs. 9, 28) and on the other side by a sub-lever 1060 (Figs. 9, 29). The sub-lever 1059 (Fig. 28) cooperates with a lug 1061 of the block bar 975 which is provided with an oblique slot 1062 acted upon by the pin 30 of the key N. The sub-lever 1060 abuts by its front end against a lug 1063 of the block bar 976. If a key ZS or ES is depressed,

the lever 62' is brought into releasing position by means of the bar 976 and of the sub-lever 1060. Upon depressing the key N, the rotation of the lever 62' takes place by means of the block bar 975 and of the sub-lever 1059.

12. Releasing the amount differential members upon taking totals

The amount differential members 65, 80 (Fig. 2) are released, as described in chapter 3, by a bow 67 extending along the lower prolongations 52 of the zero locking levers 62 being rocked in anti-clockwise direction, upon depressing a total key. The connection of said bow with the total keys $-b$, $+b$, RZ, ZS and ES is effected by the arms 1064, 1065 (Fig. 9) situated on the right-hand portion of the bow and carrying pins 1066, 1067. With the pin 1066 cooperates a double lever 1068 mounted on the bar 1040 (Fig. 9) and engaging with a lateral lug 1069 behind the lug 1041 (Fig. 14) of the bar 963 and behind the lug 1042 (Fig. 15) of the bar 964.

The pin 1067 (Fig. 9) is acted upon by a lateral lug 1070 of the sub-lever 1060. This lever cooperates with the block bar 976 (Fig. 29). As described, the block bar 963 (Fig. 14) is lifted by depressing the key RZ, the bar 964 (Fig. 15) by depressing the keys $-b$, $+b$ and the bar 976 (Fig. 29) by depressing the key ZS or ES. Upon one of these bars being lifted, the bow 67 is swung by intermediary of the sub-lever 1068 or 1060 in anti-clockwise direction whereby the amount differential members are released.

100

13. The mutual locking of the by-keys and the keys $-b$, $+b$, $-B$, $+B$, RZ

The joint throwing-in of the account totalizers takes place only during the record of amounts received or paid out. The keys 13 must therefore be set only together with the keys Ab and Zu, but not simultaneously with the keys $-b$, $+b$, $-B$, $+B$ and RZ. For the purpose of mutual locking the above-named keys there is rotatably but non-displaceably mounted on the block shaft 49 (Figs. 7, 8) a bow 1070 which is held by a spring 1071 (Fig. 7) in contact with a pin 1072 (Fig. 7) fixed on the frame of the machine. On the left the bow 1070 has two arms 1073, 1074, one of which, 1073 (Fig. 14) cooperates with the rear claw 1075 of the forked upper end of the block bar 963 while the arm 1074 cooperates by an enlarged foot 1076 (Figs. 7, 15, 16) with the claws 1075 of the block bars 964 (Fig. 15) and 965 (Fig. 16). The bars 964 and 963 are acted upon by the keys $-b$, $+b$ and RZ. The block bar 965 has lugs 1077, 1078 located in the path of the bar 905 allotted to the keys $-B$, $+B$. The bow 1070, further, shows in the range of the by-keys 13, four arms 1079, 1080, 1081, 1082 (Fig. 7), the downwardly directed lugs of which cooperating each with the frontal

110

115

120

125

130

laterally bent claws 1083 of the forked upper end of the block bars 971 (Fig. 24), 972 (Fig. 25), 973 (Fig. 26), 974 (Fig. 27) for the by-keys.

- 5 When one of the by-keys is depressed the lateral lug 1083 of the lifted block bar engages the lug of the corresponding arm 1079, 1080, 1081 or 1082 (Figs. 24 to 27) and imparts to the bow 1070 a clockwise rocking motion, so that the arms 1073 (Fig. 14), 1074 (Figs. 15, 16) engage over the claws 1075 of the block bars 963, 964, 965 (Figs. 14, 15, 16) and lock the keys $-b$, $+b$, $-B$, $+B$, RZ. If, however, one of these latter keys is depressed, the claw 1075 of the moved block bar 963, 964 or 965 engages before the arm 1073 and 1074, respectively, and prevents the bow 1070 from rocking clockwise, whereby all by-keys are locked.

20 *14. Mutually locking the by-keys and keys Ab and Zu*

An arrangement has been provided by means of which the key Ab is locked in case 25 one of the "received" by-keys 1 to 9 and 19 to 23 has been depressed, and by means of which the key Zu is locked in case another by-key has been depressed. This arrangement further causes the two kinds of "received" and "paid-out" by-keys to lock themselves mutually.

On the block shaft 49 (Fig. 7) is rotatably but not shiftably mounted a block bow 1084 (Figs. 7, 8) to the left-hand arm 1085 of which (Figs. 7, 22) is pivoted at 1086 (Figs. 11, 22) the auxiliary slide 981. This slide has a projection 1087 (Fig. 22) destined to cooperate with the bars 905 allotted to the keys Ab and Zu. The bow 1084 possesses, 35 in the range of the by-keys, four arms 1088, 1089, 1090, 1091 (Fig. 7), the arms 1088 (Fig. 24) and 1090 (Fig. 26) being forwardly directed and being opposite the lower oblique faces of the lateral lugs 1083 of the block bars 971 and 973, respectively. The arms 40 1089 (Fig. 25) and 1091 (Fig. 27) are rearwardly directed and the lower oblique faces of their lateral lugs 1092 are opposite the rear claws of the forked ends of the block bars 972 and 974 respectively. The block bow 1084 is yieldingly held, by means of a special adjusting device, in a determined middle position, in which its arms and the auxiliary bar 981 take the position shown in 45 the drawing. To this end the arm 1090 (Fig. 7) of the bow 1084 shows a pin 1093 (Fig. 26) engaged by two levers 1095, 1096 loosely mounted on a bar 1094. These two levers are connected by a spring keeping them 50 from either side in contact with the shaft 49 and keeping the pin 1093 and thus the bow 1084 in a determined middle position yielding towards both sides.

55 Upon depressing one of the by-keys 1 to 9 and 19 to 23 the block bar 971 (Fig. 24) and

973 (Fig. 26), respectively, is lifted and imparts by means of the forward arm 1088 or 70 1090 to the bow 1084 a clockwise rocking motion. This causes an upward motion of the auxiliary slide 981 (Fig. 22) the lug 1087 of 75 which moves below the bar 905 allotted to the key Ab. At the same time the rear arms 1089 (Fig. 25) and 1091 (Fig. 27) move over the lugs 1092 of the block bars 972 and 974 and lock them against an upward motion. By 80 depressing one of the "received" by-keys 13 thus the paid out by-keys and the key Ab are locked. Upon depressing one of the by-keys 10 to 18 and 24 to 27, the bow 1084 has imparted to it an anti-clockwise rocking motion whereby the auxiliary slide 981 (Fig. 22) is lowered and its lug locks the key Zu and whereby the forward arms 1088 (Fig. 24), 1090 (Fig. 26) lock, by means of the block bars 971 and 973 the "received" by-keys. 85

15 *15. Mutually locking the keys ZS, ES and RZ*

No transaction totalizer of the group S (Fig. 2) is allotted to the key RZ, from which 90 totalizer, after depressing the keys ZS, ES, as is possible with the totalizers allotted to the main keys, the total might be taken. A simultaneous depression of the key RZ and of one of the keys ZS, ES is therefore hindered 95 by a special arrangement.

The block shaft 49 (Fig. 7) carries a bow 1098 which is held in contact with the pin 1072 by a spring 1099 (Fig. 14). This bow 1098 shows on the left a downwardly directed arm 100 1100 (Figs. 7, 14) cooperating with a slot 1105 (Fig. 14) of the upper end of the bar 963 which may be acted upon by the key RZ, and shows on the right an arm 1106 (Figs. 7, 29) the lower oblique face of which is located in the path of the lug 1036 of the bar 976 acted upon by the keys ZS, ES. If the key RZ is depressed, the bar 963 moves with its slot 1105 over the arm 1100 and locks the bow 1098 against rotation so that no key ZS 110 or ES can be depressed. If, however, a key ZS, ES is depressed, then, upon upward motion of the bar 976 (Fig. 29), the bow 1098 has imparted to it, by means of the lug 1036 and of the arm 1106 a clockwise rocking motion, the arm 1100 moving over the claw 1052 (Fig. 14) of the bar 963 and locking the key RZ. 115

16 *16. Mutually locking the main keys, key HR and by-keys*

If from one of the account or transaction totalizers of the groups N_1 , N_2 , N_3 and S or from the auxiliary totalizer the total is to be 125 taken, the main or by-key in question or the key HR must be depressed, after depressing the key ZS or ES. The operation of taking a total can be taken part in by a single totalizer only, according to the construction of the machine; means are therefore provided which 130

so block the main and by-keys and the key HR upon depressing the key ZS or ES, that one key only of these keys is able to be depressed. As described in chapter 19, detent disks 917, 918 (Fig. 7) are arranged between the six main keys and between the by-keys of each row so that one key only of the six main keys or one key of each row 13 can be depressed in every case. In chapter 14 is further described a mechanism for mutually locking between the two kinds of by-keys and the keys Ab and Zu. All these locking mechanisms are not able, however, to prevent that besides a main key the key HR and a by-key is depressed and that two by-keys of the same kind in two different rows are set. In order to exclude these possibilities but to not interfere with the mutual relations of the keys in question in case no total is to be taken, the block means above-mentioned normally are out of working readiness and are brought into readiness only by depressing one of the keys ZS or ES.

The block shaft 49 (Fig. 7) has mounted on it for loose rotation and shifting motion, the two bows 1107 and 1108. The bow 1107 shows the arms 1109 to 1115. A sleeve 1116 is attached on the right to the arm 1115, in the annular groove of which sleeve engages the forked end 1117 (Figs. 7, 27, 29) of an angle lever 1120 pivoted at 1118 on a bent-portion 1119 (Fig. 7) of the key partition. The other arm 1121 of said angle lever rests on a lug 1122 (Fig. 29) of the block bar 976, to which lug it is brought in contact by a spring 1123 (Fig. 7) arranged between the bow 1107 and a pin 1124 and normally holding the bow 1107 in its right-hand end position. Upon depressing one of the keys ZS, ES, the bow 1107 (Fig. 7) is shifted towards the left into working position, by intermediary of the block bar 976 (Fig. 29) and of the angle lever 1120. Upon releasing the key in consideration, the bow automatically returns into its position of rest under the action of the spring 1123.

The bow 1108 has eight arms 1125 to 1132 (Figs. 7, 8). The arms 1131 and 1132 (Fig. 7) are embraced by the arms 1114 and 1115 of the bow 1107 so that the bow 1108 is enforced to take part in the lateral movement of the bow 1107. The bow 1108 shows at its left-hand end, a prolongation 1133 (Figs. 7, 8) projecting beyond the arm 1125 and abutting against the arm 1023 of the bow 1012 which effects together with the bow 1013 the mutual locking of the keys - b, + b by the disk 265 (Fig. 4). Between the arm 1023 and the arm 1024 of the bow 1013 is inserted a sleeve 1101 (Fig. 7) and the arm 1109 of the bow 1107 abuts from the left on the arm 1024. In this manner the bows 1012, 1013 also are enforced to take part in the lateral motion of the bow 1107.

By means of special adjusting devices the bows 1107 and 1108 are yieldingly held in both directions of rotation in a determined position, these devices being of the same construction as that employed for the bow 1084 (Figs. 26, 7) and consisting of the levers 1095 and 1096: Two levers 1136, 1137 connected by a spring 1135 cooperate with a pin 1134 of the bow 1107 (Figs. 7, 25), and two levers 1140, 1141 connected by a spring 1139 cooperate with a pin 1138 of the bow 1108 (Figs. 7, 24).

The arms 1110 (Fig. 7) of the bow 1107 and the arms 1125 of the bow 1108 cooperate, by lower oblique faces, with claws 1142 and 1143 (Fig. 20) of the block bar 969 for the key HR, the arm 1110 being directed to the rear, while the arm 1125 is directed forward. The arms 1111 (Fig. 7) of the bow 1107 and the arm 1126 of the bow 1108 cooperate with claws 1144, 1145 (Fig. 22), bent to the right, of the block bar 970 for the six main keys, the arm 1111 being directed to the rear while the arm 1126 is directed forward. With the bows in working position, upon depressing one of the main keys or the key HR, the bow 1108 has thus imparted to it a clockwise rotation and the bow 1107 a rotation in opposite sense.

With each of the four block bars 971, 972, 973, 974 (Fig. 7) of the by-keys 13 cooperate two parallel arms each, of the bows 1107 and 1108, by means of lower oblique faces. The rear arms 1112, 1129 come into alternate action with the block bar 971 (Figs. 24, 7), the same is the case with the block bar 972 (Figs. 25, 7) and the rear arms 1113, 1130, with the block bar 973 (Figs. 26, 7) and the forward arms 1114, 1131, with the block bar 974 (Figs. 27, 7) and the forward arms 1115, 1132, of the bows 1107, 1108. The direction of said arms is, as evident, opposite to each other with the two rows of by-keys for "received" (Figs. 24, 26) and with the two rows of by-keys for "paid out" (Figs. 25, 27).

Upon depressing a main key or the key HR the bows 1107 and 1108 rock in opposite sense and the arms 1129 (Fig. 24) and 1130 (Fig. 25) of the bow 1108 lock the block bars 971, 972, and the arms 1114 (Fig. 26) and 1115 (Fig. 27) of the bow 1107 lock the block bars 973, 974. By depressing one of the main keys or the key HR thus all by-keys are locked.

Upon depressing one of the by-keys of the left-hand or middle row 13, both bows rock anti-clockwise and the arms 1125 (Fig. 20) and 1126 (Fig. 22) of the bow 1108 lock the block bars 969, 970. Upon depressing one of the by-keys of the right-hand row 13, both bows rock clockwise and the arms 1110 (Fig. 20) and 1111 (Fig. 22) lock the block bars 969, 970. As the mutual blocking action of the by-keys for "received" and "paid out" is effected separately, as described in chapter 13

14, by the bow 1084, all remaining by-keys, the main keys and the key HR are being locked upon depressing a by-key.

5 17. *Mutually locking the main keys and key HR*

There is still the possibility, required for a record of first order, to depress the key HR together with another main key. In 10 order to obviate also this possibility when one of the keys ZS or ES is depressed, a bow is loosely mounted on the shaft 49, this bow consisting of two arms 1146, 1147 and a bar 1148 and being arranged between the arm 1110 (Fig. 7) of the bow 1107 and the arm 1126 of the bow 1108, and taking part in the lateral motion of the bows 1107 and 1108. Said bow is yieldingly held in a determined position by an adjusting device 15 20 25 1149, 1150, 1155 (Fig. 21) attached to its bar 1148 (Figs. 21, 7). The arm 1146 is directed forward and turns to the claw 1142 of the block bar 969 (Fig. 20) a lower oblique face, while the rear arm 1147 is opposite the claw 1145 of the block bar 970 (Fig. 22).

If a main key is depressed after the arms 1146, 1147 (Fig. 7) have reached the range of the bars 969, 970 by depression of a key ZS, ES, the key HR is locked by the arm 30 35 40 45 1146 (Fig. 20) engaging over the claw 1142 of the bar 969, if the key HR is depressed, the main keys are locked by the arm 1147 (Fig. 22) engaging over the claw 1145 of the bar 970.

35 18. *Release of the mutual locking of the keys
-b, +b*

As described in chapter 9, one of the keys 40 45 50 55 60 65 70 75 -b, +b is permanently locked by the disk 265' (Fig. 4). This locked state must be released by depressing the key ZS or ES in case the total is to be taken from the transaction totalizer allotted to said locked key. The bows 1012, 1013 (Fig. 7) mediating the locking of the keys -b, +b, are shifted to the left, as described, upon depressing a key ZS, ES, by the bows 1107, 1108. When this takes place, their arms 1023, 1024 come out out of the planes of the bars 967, 968, where- 80 85 90 95 100 105 110 115 120 125 130 by the locking action of the disk 265' (Fig. 4) onto the keys -b, +b is annulled during the time a key ZS, ES is set.

19. *Releasing the motor key*

55 The different operations of the machine are initiated by depressing the motor key M. This key can be depressed only if the other setting operations required for the operation 60 65 70 75 80 85 90 95 100 105 110 115 120 125 130 of the machine have been made before. The succession in depressing the keys, with the records of first order is the following: Amount keys, account keys, by-keys, main key in consideration, motor key. The account keys need to be depressed only in case the old state is to be recorded, and the by-

keys only in case amounts received or paid out are to be recorded. As the amount zero is also able to be recorded, for instance in recording the state $+b=0$, the depression of the account keys and the following keys is not made dependent on the prior depression of an amount key. Upon taking a sub-total from the main totalizer the key RZ and the motor key M is depressed, upon taking the total from a control totalizer the key ZS or 70 75 80 85 90 95 100 105 110 115 120 125 130 ES, one of the control totalizer keys and the motor key M are depressed. The motor key is thus usually released by the main keys and by the key RZ only, if, however, a key ZS or ES has been depressed, the release of the motor key is effected, besides by the main keys and the key RZ, also by the key HR and the by-keys.

The shaft 505 (Fig. 31) of the motor key M has fixed on it a pin 1156 cooperating with 85 the upper end, showing an oblique face 1157, of a slide 1161. This slide is acted upon by a spring 1158 and is guided, by pins 1159 and slots 1160 about vertically relative to said key shaft. The slide 1161 is in connection, by means of a pin 1162 engaging a slotted arm 1163, to a shaft 1164 mounted in the frame.

This shaft has, in the range of the row of keys 11, a rigid arm 1165 (Fig. 22) abutting 95 with its upper end to a pin 1166 of the block bar 970. When said bar is lifted by depressing one of the main keys, the shaft 1164 has imparted to it, by means of the arm 1165, a rotation whereby the slide 1161 (Fig. 31) 100 105 110 115 120 125 130 is moved out of the path of the pin 1156 of the motor key and the latter is released. When the slide 1161 has rushed upward again after the depressed main key has been released, it is pushed, when the motor key returns to rest position, downward by the pin 1156 engaging the surface 1157, and rushes anew for locking the motor key, when the pin 1156 is arrived at the level of its left-hand side.

The pin 30 of the key RZ (Fig. 23) cooperates with a projection 1167 of a double lever 1169 pivoted at 1168 on the partition. This double lever 1169 is connected to the shaft 1164 by a sub-lever 1170 engaging by 115 120 125 130 slots over a pin 1171 of the said double lever 1169, and by a pin 1172 of an arm 1173. Upon depressing the key RZ the shaft 1164 is rotated in the same manner as if a main key is depressed, and the motor key is released.

The double lever 1169 (Fig. 23) engages by a pin 1174 a slot of a lever 1175 loosely mounted on the shaft 49, the upper end of which lever is intended to cooperate with a 125 pin 1177 fixed on an arm 1176 of the bow 1070. The lever 1175 is embraced by the arms 1127, 1128 of the bow 1108 (Fig. 7) and is thus enforced to take part in the lateral shifting motion of the bow 1108. This 130

lever 1175 normally lies out of the path of the pin 1177. If, however, the bow 1108 is shifted to the left by depressing a key ZS, ES, it arrives behind the pin 1177. As described in chapter 13, the bow 1070 has imparted to it a clockwise rotation upon depressing a by-key. This rotation causes—if a key ZS or ES has been depressed before—the shaft 1164 (Fig. 23) to have imparted to it, by means of the pin 1177, levers 1175, 1169 and 1170, the motion required for releasing the motor key M.

The arm 1128 (Figs. 7, 23) of the bow 1108 shows a bent portion 1178 engaging over the lever 1175. As described, the bow 1108 is provided with a forwardly directed arm 1125 (Fig. 20) which, upon depressing the key ZS or ES enters the path of the block bar 969 and effects a clockwise rotation of the bow 1108, upon depressing the key HR. This rotation is transmitted by said bent portion 1178 (Fig. 23) onto the lever 1175 and therewith to the shaft 1164 releasing the motor key M. In this way the motor key is released, after foregoing depression of the key ZS, ES, also directly in the key HR.

If the key HR is being set, the keys ZS, ES cannot be depressed, as upon shifting the bow 1108 the arm 1125 would laterally strike the lifted claw 1142 (Fig. 20). The key HR must therefore be released by its releasing key L before a key ZS, ES is depressed and must be set anew, after depressing a key ZS, ES, if the total is to be taken from the auxiliary totalizer.

20. Releasing the main keys and key RZ

While the key HR is not locked before the beginning of a record in order to be able to effect the joint throwing-in of the auxiliary totalizer if desired, the main keys and the key RZ are locked at this time and are released only when an account key or a key ZS, ES is depressed. The shaft 957 (Figs. 7, 12, 14) mounted for rotation in the frame, has rigidly fixed to it a bow 1179 extending along upper prolongations 1180 (Fig. 14) of the block bars 592 (Fig. 12), said prolongations cooperating by V-shaped recesses with the pins 590 of the account keys 17. On the right-hand end of the shaft 957 is rigidly fixed an arm 1182 (Figs. 7, 12, 29) the upper bent extremity 1183 of which cooperates with an oblique face 1184 of the block bar 976 for the keys ZS, ES. A bow 1185 likewise rigidly fixed on the shaft 957 (Figs. 7, 12) engages over lugs 1186 (Fig. 7) of the block bars 963 (Fig. 14) for the key RZ, 964 (Fig. 15) for the keys —b, +b, 965 (Fig. 16) for the keys —B, +B and 966 (Fig. 17) for the keys Ab, Zu. A spring 1187 (Fig. 29) attached to the lever 1182 (Fig. 29) normally keeps the shaft 957 in the illustrated position in which the main keys and the key RZ are locked by the

bow 1185. Upon depressing an account key 17 or a key ZS, ES, the release of the main keys and of the key RZ takes place by the shaft 957 having imparted to it the rotation required for releasing the projections 1186 by the bow 1185, either from the block bar 592 (Fig. 12) of the account keys and the bow 1179 or from the lever 1182 (Fig. 29). The keys —b, +b, Ab, Zu can be locked, however, still by other means in a record of first order, as hereinafter described.

21. Releasing the keys Ab, Zu by the by-keys and the keys ZS, ES

In recording amounts received and paid out of a record of first order, account totalizers of the group N₁, N₂, N₃ are to be thrown into joint operation. For this purpose an arrangement is provided enabling, in a record of first order, the depression of a key Ab and Zu only when a by-key has been depressed before. The rear claw 1025 (Fig. 17) of the block bar 966 for the keys Ab and Zu is normally opposite the lower end 1188 of a lever 1189 loosely mounted on the shaft 49, so that the keys Ab and Zu normally are locked, by means of tapered faces 1153, 1154 provided on the block bar 966. The lever 1189 is held by a spring 1190 (Fig. 17) in contact with a lug 1191 of an arm 1192 which is rigidly connected to the shaft 49. The upper end of said lever engages behind a pin 1193 fixed on the arm 1074 of the bow 1070. This bow shows, as described in chapter 13, forwardly directed arms 1079 to 1082 (Figs. 7, 24 to 27) cooperating with the block bars of the by-keys so that upon depressing a by-key, the bow 1070 and, by intermediary of the pin 1193, the lever 1189 (Fig. 17) have imparted to them a clockwise rotation. Thereby the foot 1188 comes out of the path of the claw 1025 and releases the keys Ab and Zu.

The locked state of the keys Ab and Zu must, further, be released also by depressing the keys ZS, ES in order to enable the total to be taken from the transaction totalizers recording the amounts received and paid out. This is made in the following manner: If a key ZS, ES is depressed, the block shaft 49 has imparted to it, by the arm 1031 cooperating with the block bar 976 (Figs. 7, 29) and rigidly connected to the shaft 49, a clockwise rotation. This rotation has, as described in chapter 10, the first object of locking the amount keys when a total key is to be depressed but causes further in this case the lever 1189 (Fig. 17) to be taken along by the lug 1191, exactly as upon depressing a by-key, in clockwise direction and to release the locked state of the keys Ab and Zu.

22. Normal state of the machine

The last-described blocking arrangements are of a character such as to have the object of enforcing a determined setting success-

sion of the keys in one and the same operation of the machine. The blocking arrangements described hereinafter, however, relate to the mutual condition of the single records of a transaction or to the transactions themselves. The machine is so arranged that after a transaction has been finished, the four different records I to IV may be initiated as desired. When, however, one of these records has been started, the machine is enforced to execute all works to be done in this record in a determined succession, and no following record can be started before these works have been completed.

15 The state assumed by the machine and its member after finishing any transaction, is always the same, it may be denoted by "normal state".

20 The auxiliary slides 977 to 981 (Fig. 11) are decisive as to the state of the machine relating to the setting succession of the operations. The auxiliary slide 981 takes, in normal state, the position illustrated in which its lug 1087 is out of the path of the bars 905 allotted to the keys *Ab* and *Zu*.

25 The auxiliary slide 980 (Fig. 19) takes its upper position in which two lugs 1194, 1195 arranged on it lock the keys *Ab* and *Zu*, in which, further, two oblique faces 1196, 1197 lie in the path of the bars 905 of the keys *-B*, *+B* and the rear face of the lug 1009 keeps down the locking cone 1008 by means of its lug 908.

30 The auxiliary slide 979 (Fig. 17) is held, against the action of the spring 993, in its lower position by the lug 1006 of the forwardly spring-actuated locking cone 996 (Fig. 18), said lug 1006 engaging before the upper face of the lug 1007 (Fig. 17). In this lower position of the slide 979 two projections 1198, 1199 are out of the path of the bars 905 of the keys *-B*, *+B* so that the latter are not locked by the auxiliary slide 979. Two oblique faces 1200, 1205 cooperating with the bars 905 of the keys *-b* and *+b*, are likewise out of the path of said bars.

35 The auxiliary slide 978 (Fig. 11) engaging by a rod 1206 projecting on both sides, over the ends of the auxiliary slides 977 and 980, is in its upper position (Fig. 16) in which it is kept by the spring 993.

40 The auxiliary slide 977 (Fig. 15) takes its upper position, in which it engages by projections 1207, 1208, below the bars 905 of the keys *-b*, *+b* and locks them, and in which further its faces 1209, 1210 lie in the path of the bars 905 of the keys *Ab*, *Zu* and retains, with the rear face of its lug 1011 the locking cone 997 by the lug 1010 provided on this latter.

23. The setting succession in records of first order

45 As described in chapter 22, among the main keys are locked by the auxiliary slides the

keys *Ab*, *Zu*, *-b*, *+b* in the normal state of the machine so that upon initiating a record of first order by depressing amount and account keys, the bow 1185 (Fig. 7) releases the keys *-B*, *+B* only. The setting of the keys *-B*, *+B* must now effect that these keys themselves are locked after the first record has been finished, and that the keys *Ab* and *Zu* are released.

50 Upon depressing a key *-B*, *+B*, the auxiliary slide 980 is shifted downward by the faces 1196, 1197 (Fig. 19) so that its lugs 1194, 1195 release the keys *Ab* and *Zu*. The lug 1008 engages over the lug 1009 of the auxiliary slide 980 thus keeping the latter in its lower position until the locking cone 998 is again moved rearward. This takes place only if a key *-b* and *+b*, respectively, is depressed, by its bar 905 engaging the frontal face 999 of said locking cone. Any desired number of records may thus be executed for recording amounts received and paid out.

55 Upon depressing a key *-B*, *+B* the locking cone 996 (Fig. 18) is pushed to the rear by the corresponding bar 905 so that its lug 1006 (Fig. 17) releases the auxiliary slide 979, this latter moving, under the action of the spring 993, upward and particularly, at first so far as to cause the lug 1198 and 1199, respectively, to abut by its front face against the returned bar 905. In this position of the auxiliary slide 979 the rear face of its lug 1007 has already engaged before the lug 1006 of the locking cone 996 (Fig. 18) so that said cone is retained in its rear position upon the key *-B*, *+B*, respectively, being released at the end of the record. When the key *-B* or *+B* returns the auxiliary slide 979 is able to accomplish its upward motion and engages with its projections 1198, 1199 below the bar 905 of the keys *-B*, *+B* whereby the latter are locked and this until the auxiliary slide is again moved downward.

60 When for starting the second record, a key *Ab*, *Zu* is depressed, the keys *-b*, *+b*, still locked, must thereby be released but the locking of the keys *Ab* and *Zu* for the following record is prepared. Upon depressing a key *Ab*, *Zu* the auxiliary slide 977 is shifted downward and is held in this lower position by the lug 1010 of the cone 997 which has rushed forward, in which lower position the lugs 1207, 1208 of said slide release the keys *-b*, *+b*. Any desired number of records may now be initiated by depressing the keys *Ab*, *Zu* without altering the position of the auxiliary slide in any way.

65 Upon initiating, by depressing that of the keys *-b* or *+b* which has been released by the disk 265' (Fig. 4), the last section of a record, it must be attained that at the end of this section the keys *-B*, *+B* are in released state and that the key *-b*, *+b* which was depressed and released again in the meantime, and the keys *Ab*, *Zu* are in locked state. Upon de-

pressing a key $-b$, $+b$ the auxiliary slide 979 (Fig. 17) is moved downward by the bars 905 cooperating with the faces 1200, 1205, and is held in this lower position by the lug 1006 of the locking cone 996 which has rushed forward, in which lower position the lugs 1198, 1199 of said slide 979 release the keys $-B$, $+B$. The depression of a key $-b$, $+b$ further causes the locking cones 997 (Fig. 15), 998 (Fig. 19) to be pushed back so that the two auxiliary slides 977, 980 which are retained by said cones, rush upward. When this takes place, the auxiliary slide 980 (Fig. 19) engages with its projections 1194, 1195 below the bars 905 of the keys Ab , Zu and locks them. After the key $-b$, $+b$, respectively, has been released, the auxiliary slide 977 (Fig. 15) engages with its projections 1207, 1208 below the bar 905 of the keys $-b$, $+b$ and locks them also, so that after the last section of the record of first order, all the auxiliary slides are brought back into normal state.

The account number is the same for the duration of an ordinary transaction. In order to be obliged to set it one time only, and in particular before depressing the key $-B$, $+B$ respectively, the depression of a key $-B$, $+B$ causes the account keys 17 to be locked and to be released only after the operation initiated by depressing a key $-b$, $+b$ has been accomplished.

On the pin 1212 of the key partition is pivoted a double-armed lever 1213. The front end of this lever rests on an abutting face 1211 (Fig. 16) of the block bar 965 for the keys $-B$, $+B$, while its rear end is in contact with a pin 1214 of a thrust bar 1215. This bar is guided, by means of a slot 1216 on the cross bar 985 and embraces by a slot 1217 of its lower end a pin 1218 fixed on the double lever 954 rigid on the shaft 38 (Figs. 14, 12) the other arm of which lever abuts against a pin 956 of the locking bow 950 for the account keys. A spring 1219 (Fig. 14) normally keeps the thrust bar 1215 in its upper position in which the front face of a nose 1220 (Fig. 14) of a locking piece 1221 abuts against the rear face of the upper end of the bar 1215. Said locking piece is pivoted on a pin 1222 fixed in the wall 987 (Fig. 11). It shows an abutting face 1223 for the rods 905 of the keys $-b$, $+b$, extending in parallel to the frontal face of the locking cone 997, and is acted upon in clockwise direction by a spring.

When a key $-B$, $+B$ is depressed, the block bar 965 (Fig. 16) is shifted upward and the bar 1215, is shifted downward. by the intermediary of the double lever 1213, whereby the lever 954 (Fig. 14) has imparted to it a clockwise rotation and the locking bow 950 an opposite rotation. The bow 950 engages behind the lugs 947 of the locking bars 591 of the account keys thus causing the

latter to be locked. At the same time the drive for the release of the account keys is interrupted by the releasing bow 910 being shifted by means of the angle lever 962.

Upon the thrust bar 1215 moving down the locking piece 1221 is released, it rushes forward so that its lower face will engage with its nose 1220 over the upper end of said bar 1215 and locks the latter, the locking bow 950 and the releasing bow 910 by the described connections in their displaced position until a key $-b$, $+b$ will be depressed. When a key $-b$, $+b$ is depressed, the rod 905 engaging the abutting face 1223 of the locking piece 1221 (Fig. 14) returns again said piece whereafter the thrust bar 1215, the locking bow 950 and the releasing bow 910 return to their initial positions by the action of their springs.

24. Setting succession in records of second order

In order to release the operation of the machine for taking a sub-total from the main totalizer, the key RZ and the motor key must be depressed. A sub-total from the main totalizer is able to be taken only with a record of first order and, particularly, before the last section thereof which is caused by depressing a key $-b$, $+b$. The locking of the key RZ in the normal state of the machine and in taking totals from the control totalizers is effected by the blocking operation between the account keys and the key RZ, as described in chapter 20. As long as account keys are being depressed, the key RZ is in released state and this is the case, as described in chapter 23, during a record of first order. The sub-totals from the main totalizer may thus be taken before or after any desired operation of the machine has been initiated by the key Ab or Zu .

25. Setting succession in records of third order

For taking a sub-total or grand total from one of the control totalizers a key ZS, ES of the corresponding control totalizer key and the motor key must be depressed. As described in chapter 19, the key HR, if set, must be released before a key ZS, ES can be depressed. Further, due to the detent devices 917, 918 (Fig. 7) existing between the keys 12 the key N, if set, must be released before depressing a key ZS, ES. In order to render impossible the depression of a key ZS for the duration of a record of first order, these keys are locked for this time. The right-hand end of the shaft 38 (Fig. 29) carries a rigid arm 1228 showing a nose 1229. This latter cooperates with a lug 1230 of the block bar 976 for the keys ZS, ES. As described in chapter 23, the shaft 38 has been rocked clockwise, for the duration of a record of first order, in order to lock the account keys 17, by the dou-

ble lever 954 (Fig. 14). Owing to this rocked state the nose 1229 engages over the lug 1230 and locks the keys ZS, ES for the duration of a record of first order against being depressed. As described in chapter 20, the bow 1185 (Fig. 7) locking the main keys releases the block bars of these keys upon depressing a key ZS, ES. Now, by depressing a key ZS, ES, the normal locking of the main keys $-b$, $+b$, Ab, Zu must be interrupted for the duration of a record of third order, this release being effected by the auxiliary slides 977 (Fig. 15), 980 (Fig. 19), as described in chapter 22. This interruption is caused by the auxiliary slide 978 (Figs. 11, 16) which engages by the rod 1206 over the ends of the auxiliary slides 977, 980 (Fig. 11). The upper end 1224 of the auxiliary slide 978 cooperates with a lug 1225 of the arm 1192 rigid on the shaft 49 (Fig. 11). The shaft 49 has imparted to it, upon depressing a key ZS, ES, a clockwise rotation by intermediary of the block bar 976 (Fig. 29) and of the forwardly directed arm rigid thereon. This rotation causes the lug 1225 (Fig. 16), connected to the shaft 49, to shift down the auxiliary slide 978 and, by the intermediary of the cross bar 1206 also the two auxiliary slides 977 (Fig. 15) and 980 (Fig. 19). The amplitude of this shifting motion is so chosen that the projections of the slides 977 (Fig. 15) and 980 (Fig. 19) will release the keys $-b$, $+b$ and Ab, Zu, but not the corresponding locking cones 997 (Fig. 15), 998 (Fig. 19). Upon releasing the key ZS and ES, respectively, the shifted auxiliary slides 977, 978, 980 (Fig. 11) return again into normal position.

By depressing a key $-B$, $+B$ the locking of the account keys is maintained for the duration of a record of first order by the locking piece 1221 (Fig. 14) engaging by the nose 1220 over the upper end of the thrust bar 1215 and maintaining it in its lower position.

In order to prevent the depression of a key $-B$, $+B$ taking place in taking a total from the transaction totalizers $-B$, $+B$, from effecting the described barring operation of the locking mechanism for the account keys, the locking piece 1221 (Fig. 14) is provided with a pin 1226 (Figs. 14, 11) cooperating with a lug 1227 (Figs. 11, 15) of the auxiliary slide 977. Upon depressing a key ZS, ES, the auxiliary slide 977 is moved down also, by intermediary of the shaft 49, the auxiliary slide 978 (Fig. 11) and the bars 1206. In consequence thereof the lug 1227 engages, as long as a key ZS, ES is being set, over the pin 1226 and prevents the locking piece 1221 from rushing forward, upon depressing a key $-B$, $+B$, and effecting the locking of the account keys for the following operations of the machine.

26. Setting succession in records of fourth order

The recording of addenda can only be made in common with a record of first order. The key N cannot be depressed together with a key ZS, ES, owing to the action of the detent device 917, 918 (Fig. 7) interposed between these keys. In order to prevent the key N, during a record of first order, from being either depressed or released, the rigid arm 1228 mounted on the right-hand end of the shaft 38 (Fig. 28) cooperates by its nose 1229 with a lug 1230 of the block bar 975 for the key N. The rocked state of the shaft 38 existing during a record of first order, as described in chapter 23, causes the nose 1229 (Fig. 28) to engage over the lug 1230 when the key N is not being depressed, and to engage below it when the key N is in depressed state. In the first-mentioned case the key N is locked against being depressed by means of its pin 30 and slot 1062, in the second case it is locked against being released. Upon rocking the shaft 38, after a record of first order has been completed, back into their initial position, the nose 1229 releases the lug 1230 of the block bar 975 and the key N is able to be depressed and released again. As will be seen, the key N must be depressed before the key $-B$, $+B$, respectively, has been set.

The connection of the key N with the totalizer control mechanism, to throw them out, is effected by the double lever 397 (Fig. 28) engaging by its pin 1231 and slot the block bar 975.

27. The item counter

The item counters serve for recording the number of depressions of the main and by-keys. This record is to be made with records of first order only. Special means are therefore provided which interrupt the driving mechanism of the item counter during the other records.

The item counters 15 and 16 each consist of three counting wheels 1234 (Fig. 33) the ciphers of which may be read through holes in the casing and these wheels are connected to one another by a suitable tens transfer mechanism. The counting wheels 1234 are mounted on shafts 1235 rigidly mounted in a frame which is formed by two plates 1236, 1237 and bolts 1238 connecting them (Figs. 7, 9, 32). Four of these frames are arranged, in all, in the machine. The left-hand frame (Fig. 7) carries six item counters for the main keys, the three right-hand frames each show nine item counters destined for the by-keys. The plates 1236 (Fig. 32) of each frame possess two slots 1239, 1240 engaged by pins 1241, 1242 rigidly fixed on the key partitions 921. A third pin 1244 rigid on the partition 921 abuts from the rear on a

lower prolongation 1243 of the plate 1236. Owing to the above-described guiding means the frame is able to execute, together with the item counters, a small down and up motion.

5 A spring 1245 attached between the frame and the partition 921, tends to keep the frame in its upper position. A rod 1247, passing through a prolongation 1246 of each plate 1236 and connecting all the frames to each other, engages in slots 1248 of two eccentric members 1249 surrounding two eccentrics 1250 (Fig. 32, 7) rigid on the shaft 42. A lever 1255 mounted on the eccentric member 1249 (Figs. 32, 28, 29) is normally held in engagement with the rod 1247 by its upper hook-shaped portion 1256, so that the rod 1247 and therewith the item counters are enforced to take part in the down and up movement of the eccentric member 1249. Lugs 1258 (Figs. 28, 29) of the levers 1255 cooperate with the lower ends of two levers 1260 rigid on a shaft 1259. The right-hand of these levers 1260 (Figs. 28, 29) carries a roll 1261 which cooperates with a tapered face 1262 (Fig. 28) of the block bar 975 influenced by the key N, and with a tapered face 1263 (Fig. 29) of the block bar 976 influenced by the keys ZS, ES.

At the right-hand side of each units wheel 30 of the item counters there is mounted for rotation on the shaft 1235 a pawl carrier 1264 (Figs. 33, 32) normally abutting under the action of a spring 1265 by a lug 1266 against a tongue 1267 of the plate 1236. The pawl carrier 1264 carries by means of a pin 1268 (Fig. 33) a spring-actuated pawl 1269 engaging the teeth of the units wheel and causes the item counter to be fed. A counter-pawl 1270 prevents the counting wheels from returning. The lugs 1266 (Figs. 33, 32, 7, 9) are such as to strike, upon the downward motion of the frame, the pins 902 of the depressed keys. If, therefore, one of the main or by-keys has been depressed and its pin 902 has been brought into the path of the lug 1266, the pawl carrier 1264 is stopped upon the downward motion of the whole frame effected, by the eccentric drive 1250, 1249 (Fig. 32), during the operation of the machine. This causes a rotation of the carrier 1264 (Fig. 33) on the shaft 1235 of such an amount such as to cause the units wheel to be fed by one unit by the pawl 1269. As it will be seen, two or more item counters can be fed at the same time.

The hook-shaped lever 1255, 1256 (Fig. 32) has the object of interrupting the drive of the item counters with records of third and fourth order. With records of second order no feeding motion of item counters takes place per se, as the key RZ has no item counter allotted to it. Upon depressing a key N, ZS or ES, the upward motion of the tapered faces 1262 (Fig. 28) or 1263 (Fig. 29) causes the levers 1260 to rock, said levers

displacing to the rear, by means of the lugs 1258, the levers 1255 so that their hooks 1256 come out of engagement with the rod 1247. During the next operation of the machine no down and up motion of the item counter, ⁷⁰ frame takes place whereby the feeding motion of the item counters allotted to the depressed main and by-keys is left undone.

28. Mode of operation

75

In the following will be described, in bold outline, the operation of the key blocking means with the four different records. In order to avoid the repeated description of the different modes of operation of the different mechanisms of the machine, reference is made to the forgoing corresponding chapters. ⁸⁰

In the normal state of the machine the differential members 65 (Fig. 2) of the amount differential mechanism, chapter 3, and the differential members 251, 252 and 253 (Fig. 5) of the transaction differential mechanism take their upper extreme positions in which they are locked by the zero locking levers 62 (Fig. 2) and 62' (Fig. 5). As to the keys, ⁹⁰ the six main keys 11, the key RZ and the motor key M are in locked state, all remaining keys are released (chapter 22). The operator has therefore free choice of initiating, by depressing amount and account keys, a record of first order or, by depressing one of the keys ZS, ES, a record of third order or, by depressing the key N, a record of fourth order. ⁹⁵

Record of first order.—Introduction of the old state

The depression of the amount keys ¹⁰ causes the corresponding amount differential members 65 (Fig. 2) to be released by the zero locking levers 62 (chapter 3) and all the total keys $-b$, $+b$, RZ, ZS, ES to be blocked (chapter 19) as far as they are not yet in blocked state (chapter 10). ¹⁰⁵

The depression of the account keys causing the account number to be set, produces the release of the main keys and of the key RZ by the bow 1185 (Figs. 7, 12; chapter 20). The keys Ab, Zu, $-b$, $+b$, however, still remain locked by the auxiliary slides 980 (Fig. 19) and 977 (Fig. 15; chapter 22), so that the keys $-B$, $+B$ and RZ only have been released. ¹¹⁰ ¹¹⁵

The depression of the key $+B$ causes to be blocked: the other main keys 11 and the key RZ (chapter 6) as far as this latter has not yet been blocked, as well as the by-keys (chapter 13), so that account totalizers will not be able to be thrown-in with this operation. The depression of the key $+B$ further causes: the transaction differential member 251 (Figs. 10, 5; chapter 11) to be released, the keys Ab and Zu to be released by their auxiliary slide 980 (Fig. 19; chapter 23), the account keys 17 to be locked and their release to be put off till the end of an operation started by one of the ¹²⁰ ¹²⁵ ¹³⁰

keys $-b$, $+b$ (chapter 23), the locking of the keys $-B$, $+B$ (chapter 23), taking place at the end of the present operation, to be prepared, the key N to be locked against depression and release during the record of first order (chapter 26), the keys ZS , ES to be locked against being depressed during the record of first order (chapter 25) and the motor key M to be released by the slide 1161 (Fig. 31; chapter 19).

By depressing the motor key all keys are blocked by means of the bow 928 (Fig. 31), the bars 931, 937 and the bows 46, 944, as far as they have not yet been blocked (chapter 7) and the operation of the machine is initiated. All keys remain blocked during the operation (chapter 7). The motor key blocks itself. If the motor key is kept depressed, any new operation of the machine cannot be initiated.

At the beginning of the operation the actuation of the transaction totalizer takes place in which only the differential member 251 (Fig. 5) is lowered into the position corresponding to the key $+B$.

The actuation of the amount differential mechanism now takes place, whereby the amount differential members are moved down to strike the set amount keys, after which the printing and display wheels are positioned corresponding to their differential members 65. Upon the return movement of the amount differential members the set amount is transmitted additively to the transaction totalizer $+B$ and to the main totalizer. At the same time takes place the return of the positioned transaction differential member 251 (Fig. 5) to its upper extreme position.

The item counter drive causes the item counter for the key $+B$ to be fed by one unit (chapter 27). At the end of the operation of the machine all keys are unlocked by the locking bows 46, 944 (Fig. 31, chapter 7) and the set keys return to unset position, except the key HR (chapter 5). When this takes place, the zero locking levers 62, 62' (Figs. 2, 5) reach again their locking position in which they lock the returned differential members. After the released motor key M has reached its position of rest, it is locked anew by the slide 1161 (Fig. 31, chapter 19). The key $+B$ is locked too, after having reached its position of rest (chapter 23). The keys Ab and Zu which had been released, by depression of account keys 17, from the bow 1185 (Figs. 7, 12, chapter 20), have been released, further, from the corresponding detent device 917, 918 by the key $+B$ returning, these keys are however still blocked by the lever 1189 (Fig. 17, chapter 21). The keys N , ZS , ES are blocked by the arm 1228 (Figs. 28, 29) so that at the end of the first operation of the machine the amount

and by-keys and the key RZ have been released, besides the key HR .

Record of first order.—Introduction of amounts received and paid out

When the key HR has been set, by means of the lever 1052 (Fig. 20), the auxiliary totalizer is thrown in. The amount of transaction which may be assumed to be an amount to be paid in, is now set by means of the amount keys. By depressing these keys the corresponding amount differential members 65 are released (chapter 3) and all total keys are locked, as far as they have not yet been locked (chapter 10). Thereupon a by-key 13 is depressed which is allotted to the kind of the receipt. By depressing the by-key 13 the corresponding transaction differential member 253 is released (chapter 11) and the by-keys 10 to 18 and 24 to 27 allotted to amounts to be paid out, and the key Ab are locked (chapter 14), while the key Zu is released.

The depression of the key Zu causes the keys $-b$, $+b$ to be released from the auxiliary slide 977 (Fig. 25, chapter 23). The keys $-b$, $+b$ remain, however, locked till the end of the operation of the machine, by the detent devices 917, 918 (chapter 6). The depression of key Zu causes further the transaction differential members 251 and the motor key M to be released (chapters 11, 19).

To initiate the operation the motor key M is depressed whereby all keys are blocked (chapter 7). At the commencement of the operation the transaction differential mechanism is actuated, whereby the transaction differential members 251 and 253 and the appertaining printing and display wheels and totalizer controlling mechanism are put into the position corresponding to the keys Zu and the depressed by-key.

Now the actuation of the amount differential members takes place which members are moved down until they strike the set keys. After this the amount is transmitted to the display and printing wheels, the main totalizer, the transaction totalizer Zu and the selected account totalizer. At the end of that operation all keys are released from the locking bows 46, 944 (Fig. 31, chapter 7) and the set keys are returned except the account keys (chapter 23) and the key HR (chapter 6), the returned differential members being locked again by their zero locking levers. At the end of the operation the amount keys, the by-keys, the keys HR , RZ and $-b$, $+b$ have been released as well as the corresponding releasing keys, but all remaining keys are locked. The operator is thus free to record still further amounts received or paid out, to take the sub-total from the main totalizer or to record the new state b .

Record of first order.—Printing the new state of account

After the operation of the machine representing an introduction of amounts *Zu* or *Ab* 5 all keys are blocked except the keys $-b$, $+b$, *Ab*, *Zu*, the amount and by-keys, the keys *RZ*, *HR* and the corresponding releasing keys.

To initiate the last operation of the record of first order serving for taking the total from the main totalizer, one of the keys $-b$, $+b$ has to be depressed. As the main totalizer contains a positive total, the key $-b$ is in locked state (chapter 9). The depression 10 of the key $+b$ causes the amount and by-keys to be locked (chapters 10, 13), the key *RZ* to be locked by detent device 917, 918 of the key row 11 (chapter 6) and causes further the release of the amount differential members 20 65, 80 (Fig. 2) from their zero locking levers (chapter 12) and the release of the motor key (chapter 19). By depressing the key $+b$ the locking of the account keys 17 and the delay of its release is annulled (chapter 25). At the same time takes place the release of the keys *N*, *ES*, *ZS* by the shaft 61 (Figs. 28, 29, chapters 25, 26). The auxiliary slides and cones 979, 997, 998 (Figs. 17, 15, 30 19) are so influenced as to lock the keys *Ab* and *Zu* and to prepare the locking of the keys $-b$, $+b$ and the release of the keys $-B$, $+B$ (chapter 23).

Upon depressing the motor key, the locking of all keys hitherto still unlocked, takes place (chapter 7) as well as the start of the operation. At the commencement thereof the transaction differential mechanism is actuated, the differential member 251 and the 35 appertaining parts of the printing, display and totalizer governing mechanisms being positioned into the position corresponding to the key $+b$. After this the total contained in the main totalizer by means of the 40 differential members 65 is transmitted to the printing and display mechanism and to the transaction totalizer $+b$, whereby the main totalizer is zeroized. The actuation of the item counter causes the item counter (chapter 45 27) allotted to key $+b$ to be fed. At the end of the operation of the machine all keys are unlocked from the blocking bows 46, 944 (Fig. 31, chapter 7) and the set amount and 50 account keys and the key $+b$ are released (chapters 5 and 23). The returned differential members are locked anew by their zero locking levers 62 and 62', respectively (Figs. 2, 5, chapters 3, 11, 12). After the operation 55 of the machine has been completed, the machine is in normal state (chapter 22) in which the amount keys, account and by-keys and the keys *HR*, *N*, *ES*, *ZS* and the corresponding releasing keys are in released state, while the 60 remaining keys are in locked state.

Record of second order

In order to be able to inform the customer, during the course of a series *Zu*- and *Ab*-records, about the intermediate state of account just existing, the sub-total can be taken from the main totalizer. In the normal state of the machine the key *RZ* is locked and is released only after an account key 17 is depressed (chapter 20), but is locked again by 70 depressing an amount key (chapter 20) so that this key is in the released state only in the intervals before and after the operations of an ordinary record destined for introducing *Zu*- and *Ab*-amounts.

If the key *RZ* is depressed in these intervals, to take a sub-total from the main-totalizer, this depression causes the amount keys 10 to be locked (chapter 10), none of these keys being allowed to be set upon depressing the key *RZ*, and causes, further, the by-keys (chapter 13) and the main keys (chapter 6) to be locked. The keys *N*, *ZS*, *ES* and the account keys 17 already are locked in their setting positions (chapters 23, 25, 26). The depression of the key *RZ* further causes the transaction differential members 251 (Fig. 25), the amount differential members 65, 80 and the motor key *M* to be released (chapters 11, 12, 19).

The depression of the motor key causes the keys *RZ* and *HR* (chapter 7), still unlocked, to be locked and the operation of the machine to be started.

In the course of the operation the total contained in the main totalizer is transmitted to the printing and display wheels. Said total may be positive or negative. At the end of the operation all keys are unlocked from the locking bows 46, 944 (Fig. 31, chapter 7) and the key *RZ* is released whereby, after the operation has been completed and the motor key has been locked again (chapter 19) all parts of the machine take exactly the same position as at the beginning of the operation so that the record of first order may be continued. The actuation of the item counters had not been influenced, as no item counter is allotted to the key *RZ*.

Record of third order

The record of third order has for its purpose to take a sub or grand total from one of the control totalizers that is from one of the account or transactions totalizers or from the auxiliary totalizer.

The record of third order is initiated by depression of a key *ZS*, *ES*. If the key *HR* was set, it must be released (chapter 19). The same applies to the key *N* (chapter 6). Upon depressing a key *ZS*, *ES* the other keys of the row 12 are locked (chapter 6) as well as the amount keys (chapter 10), while the amount differential members are released (chapter 12). The said depression further causes: the key *RZ* to be locked (chapter 15),

the mutual locking of the keys $-b$, $+b$ to be annulled (chapter 19), the keys Ab and Zu to be released (chapter 21), the transaction differential member 252 to be released (chapter 11), the main keys to be released from the bow 1185 (chapter 20), the keys $-b$, $+b$, Ab , Zu to be released from their auxiliary slides 977 (Fig. 15) and 980 (Fig. 19, chapter 25), the locking device, dependent on the keys b and B , for the account keys to become inoperative, the main and by-keys and the key HR to mutually lock themselves (chapter 16), the item counter drive to be thrown-out (chapter 27) and the by-keys and the key HR to become releasing keys for the motor key M (chapter 19).

All control totalizer keys are thus released and so blocked that one of them only can be depressed, all the other keys being locked. 20 By depressing one of the control totalizer keys the corresponding transaction differential member and the motor key is released (chapters 19, 11).

It may be assumed that grand-total is to be taken from the totalizer Ab . By depressing the key Ab the differential member 251 (Fig. 5) and the motor key is released. By depressing the latter all keys are locked and the operation of the machine is released (chapter 7). In the course of this operation the transaction differential members 252 and the appertaining parts of the printing-, display- and totalizer governing-mechanisms are positioned corresponding to the keys Ab and ES . After this the total contained in the transaction totalizer is transmitted to the printing and display mechanism zeroizing the totalizer Ab .

Upon the release of the key ES taking 40 place at the end of the operation, the blocking operations caused by the depressing of this key, are annulled (chapters 16, 25). After the operation of the machine has been finished, the machine takes again the normal state (chapter 22).

If the key ZS had been depressed, the amount differential members remain coupled with the thrown-in totalizer even during the return into their upper extreme position. 50 In other respects the mode of operation in record of third order is the same as the hereinbefore described.

In taking totals from the auxiliary totalizer, wherein after depressing the key ES or 55 ZS the key HR is set, the machine throws itself over, in case the auxiliary totalizer contains a negative total, into the state for taking negative totals in the same manner as described with records of second order.

Records of fourth order

These records serve for recording in the book a record made in an account in absence of the book. No action of the control totalizers takes place. The main totalizer only

enters into action to calculate the new state and to obviate the separate setting thereof which could be made from the statements given by the card. The record of fourth order thus takes place like that of first order 70 in which all control totalizers are at rest and the impression is made in the book only: The amounts received and paid out only and the new state of account will be printed with the sign N . 75

To initiate a record of fourth order the key N is depressed, this being possible in the normal state of the machine only (chapters 26, 6). The control totalizers hereby remain thrown out for the time the key N is 80 being set. The depressing of the key N

causes further the item counter drive to be thrown out (chapter 27) and the transaction differential member 252 (Fig. 5) to be released, said member having the task of positioning the type N in the printing mechanism. Upon initiating the first operation of the record by depressing one of the keys $-B$, $+B$ the key N is locked. This locked state is annulled only during the last operation of the record by depressing a key $-b$ or $+b$ (chapter 26). During the first operation the old state is transmitted to the main totalizer, and no impression takes place. In the operations for recording 90 amounts received and paid out these amounts are transmitted additively or subtractively to the main totalizer and are printed on the control strip together with the type N . A transmission of said amounts to the account 95 totalizers does not take place although by-keys have been set. During the last operation the impression of the positive or negative new state is made on the control strip, the main totalizer being at the same time 100 zeroized.

While the form of mechanism herein shown and described is admirably adapted to fulfil the objects primarily stated, it is to be understood that it is not intended to 110 confine the invention to the one form of embodiment herein shown and described, as it is susceptible of embodiment in various forms, all coming within the scope of the claims which follow. 115

Claims:

1. In a machine of the class described, a totalizer, amount keys, keys for setting the machine for one kind of operation, keys for setting the machine for another kind of operation, keys for setting the machine for taking totals, means for causing an operation of the machine, means for enforcing an actuation of said last-mentioned means after the setting of any one of said setting keys, and means for enforcing the setting of the setting keys for successive operations in a definite sequence. 125

2. A machine according to claim 1 in which the means for enforcing the setting 130

of the setting keys for successive operations in a definite sequence is so constructed as to permit said first-mentioned setting keys to be set only once, said second-mentioned setting keys to be set any number of times in succession, and said total-taking setting keys to be set only once.

3. The combination with the parts specified in claim 1 of means for locking said first-mentioned setting keys at the end of an operation set up by them for the time of the following operations of a succession of operations.

4. The combination with the parts as specified in claim 1 of a spring-actuated locking slide, lugs on said slide locking said first-mentioned setting keys in the position of rest of said slide and unlocking the same in the shifted position thereof, and a spring-actuated member adapted to maintain said slide in shifted position and so cooperating with said first-mentioned setting keys that it releases said slide upon said keys being depressed, said slide returning to position of rest.

5. The combination with the parts specified in claim 1 of locking means for said second-mentioned setting keys controlled by said first-mentioned setting keys so that the former are released upon depression of the latter.

6. The combination with the parts specified in claim 1 of a spring-actuated locking slide, a spring-actuated member adapted to maintain said slide in shifted position, and lugs on said slide adapted to lock said second-mentioned setting keys when said slide is in initial position, inclined faces on said slide so cooperating with said first-mentioned setting keys that said slide is shifted upon depressing said keys.

7. The combination with the parts specified in claim 1 of locking means for said total-taking setting keys controlled by said second-mentioned setting keys so that the former are released on depression of the latter.

8. In a machine according to claim 1 a spring-actuated locking slide, a spring-actuated member adapted to maintain said slide in shifted position, lugs on said slide locking said total-taking setting keys when said slide is in position of rest, and inclined faces on said slide so cooperating with said second-mentioned setting keys that said slide is shifted by depressing said second-mentioned keys.

9. The combination with the parts specified in claim 1 of locking means for said second-mentioned setting keys, means controlled by said first-mentioned setting keys for releasing said locking means, and means controlled by said total-taking setting keys for causing said locking means to lock said second-mentioned setting keys.

10. The combination with the parts specified in claim 1 of a spring-actuated locking slide, a spring-actuated member adapted to maintain said slide in shifted position, and lugs on said slide adapted to lock said second-mentioned setting keys when said slide is in position of rest, inclined faces on said slide so cooperating with said first-mentioned setting keys that said slide is shifted upon depressing said keys, said spring-actuated member so cooperating with said total-taking setting keys that it releases said slide when said keys are depressed, whereby said slide locks said second-mentioned setting keys.

11. The combination with the parts specified in claim 1 of locking means for said total-taking setting keys, and means controlled by said total taking setting keys for rendering said locking means effective at the close of an operation initiated by said keys.

12. The combination with the parts specified in claim 1 of locking means for said second-mentioned setting keys, means for disengaging said locking means controlled by depression of said first-mentioned setting keys, locking means for said total-taking setting keys, and means controlled by depression of said total-taking setting keys for rendering both said locking means effective.

13. The combination with the parts specified in claim 1 of locking means for said first-mentioned setting keys, and means controlled by said total-taking setting keys for releasing said locking means.

14. The combination with the parts specified in claim 1 of a spring actuated locking slide, lugs on said slide locking said first-mentioned setting keys when said slide is in position of rest, a spring actuated member adapted to retain said slide in a shifted position and so controlled by said first-mentioned setting keys that it releases said slide upon depression of said keys, and inclined faces on said slide so cooperating with said total-taking setting keys that said slide is shifted by depression of the latter keys.

15. The combination with the parts specified in claim 1 of further setting keys, locking means therefor, and operative connections between said locking means and said succession enforcing means enabling said setting keys to be locked during said definite succession of operations of the machine.

16. The combination with the parts specified in claim 1 of further totalizers, operation keys therefor, locking means for said keys, and operative connections between said means and said succession enforcing means whereby said operation keys are locked both against depressing and being released during said definite succession of operations of the machine.

17. The combination with the parts specified in claim 1 of a shaft, an arm rigid thereon, a spring-actuated rod pivoted on said arm,

a spring-actuated locking member adapted to maintain said rod in shifted position, connections between said rod and said first-mentioned setting keys adapted to shift said rod upon depressing one of said first-mentioned setting keys, and an abutting face on said locking member so cooperating with said total-taking setting keys that said member releases said rod by depressing one of said total-taking setting keys.

18. The combination with the parts specified in claim 1 of a shaft, an arm rigid thereon, a spring-actuated rod pivoted on said arm, a spring-actuated locking member adapted to maintain said rod in shifted position, connections between said rod and said first-mentioned setting keys adapted to shift said rod upon depressing one of said first-mentioned setting keys, an abutting face on said locking member so cooperating with said total-taking setting keys that said member releases said rod by depressing one of said total-taking setting keys, account keys for setting the account numbers, a locking means for said account keys, and an arm rigid on said shaft and cooperating with the locking means for said account keys.

19. The combination with the parts specified in claim 1 of a shaft, an arm rigid thereon, a spring-actuated rod pivoted on said arm, a spring-actuated locking member adapted to maintain said rod in shifted position, connections between said rod and said first-mentioned setting keys adapted to shift said rod upon depressing one of said first-mentioned setting keys, an abutting face on said locking member so cooperating with said total-taking setting keys that said member releases said rod by depressing one of said total-taking setting keys, further totalizers, operation keys therefor, an addendum key for rendering said operation keys inoperative, block bars influenced by said last-named keys, lugs on said bars, and an arm rigid on said shaft cooperating with said lugs.

20. The combination with the parts specified in claim 1 of a shaft, an arm rigid thereon, a spring-actuated rod pivoted on said arm, a spring-actuated locking member adapted to maintain said rod in shifted position, connections between said rod and said first-mentioned setting keys adapted to shift said rod upon depressing one of said first-mentioned setting keys, an abutting face on said locking member so cooperating with said total-taking setting keys that said member releases said rod by depressing one of said total-taking setting keys, a sub-total key for said totalizer, locking means therefor, and operative connections between said means and said shaft adapted to release said key upon depressing one of said first-mentioned setting keys and to lock it upon depressing one of said second-mentioned setting keys.

21. In a machine of the class described, a

main totalizer for registering various kinds of operations, secondary totalizers each for registration of one or more of said kinds of operation, main keys for setting the machine for said various kinds of operations, special keys for setting the machine for taking totals from said secondary totalizers, means for enforcing the setting of said main keys for successive operations in a definite sequence, and means controlled by said special keys for rendering inoperative said last-mentioned means.

22. In a machine of the class described, a main totalizer for registering various kinds of operations, secondary totalizers each for registration of one or more of said kinds of operation, main keys for setting the machine for said various kinds of operations, special keys for setting the machine for taking totals from said secondary totalizers, means controlled by depression of one of said main keys for enforcing the setting of said main keys for successive operations in a definite sequence, means for locking said special keys upon initiation of said succession of operations, and means controlled by said special keys for releasing all said main keys and rendering said sequence enforcing means inoperative.

23. The combination with the parts specified in claim 1 of a shaft, an arm rigid thereon, a spring-actuated rod pivoted on said arm, a spring-actuated locking member adapted to maintain said rod in shifted position, connections between said rod and said first-mentioned setting keys adapted to shift said rod upon depression of one of said first-mentioned setting keys, an abutting face on said locking member so cooperating with said total-taking setting keys that said member releases said rod by depressing a key of third kind, a pin on said locking member, special keys, a slide moved by depressing said special keys, and a lug on said slide so cooperating with said pin as to engage over said pin upon depression of one of said special keys, whereby said locking member is hindered from rocking and locking said rod upon depression of one of said first-mentioned setting keys.

24. In a machine of the class described the combination of a main totalizer and an auxiliary totalizer for additions and subtractions, transaction totalizers, account totalizers, main keys adapted to simultaneously control an operation of said main totalizer and to throw in a transaction totalizer, an auxiliary totalizer key adapted to throw in said auxiliary totalizer upon certain amount operations of said main totalizer occurring, by-keys for throwing in said account totalizers, total keys for said auxiliary totalizer, for said transaction and account totalizers, account keys for setting the account number, an addendum key destined to annul the

- throwing in of said transaction totalizers, among said main keys: keys for amounts to be set in first place, keys for amounts to be set in second place and keys for taking grand totals from said main totalizer; a sub-total key for said main totalizer, locking means between said account keys, main keys and said sub-total key, a locking device locking all keys during the operation of the machine, mutual locking means between said main keys; all said locking means being so arranged that in normal state of the machine are released: the by-keys, account keys, total keys, the auxiliary totalizer key and addendum key while are locked by said account keys: the main keys for amounts to be set in first place and said sub-total key and besides, by said locking means provided between said main keys: the other main keys.
25. In a machine of the class described the combination of keys arranged in a row, a slide, inclined faces thereon so cooperating with certain keys that said slide is shifted against spring action by depressing said keys, lugs on said slide adapted to lock against depression certain other keys in the position of rest of said slide, but to release them upon depression of said first-named keys, and a spring-actuated member so cooperating with said slide that the latter is retained in its shifted position, said member further so cooperating with said second-named keys that it releases said member, upon depression of said second-named keys, so as to cause said slide to return to position of rest.
26. In a machine of the class described the combination of a main totalizer and an auxiliary totalizer both destined for additions and subtractions, transaction totalizers, account totalizers, main keys adapted to simultaneously control an operation of said main totalizer and to throw in a transaction totalizer, an auxiliary totalizer key adapted to throw in said auxiliary totalizer upon certain amount operations of said main totalizer occurring, by-keys for throwing in said account totalizers, total keys for said auxiliary totalizer, for said transaction and account totalizers, account keys for setting the account number, an addendum key destined to annul the throwing in of said transaction totalizers, a sub-total key for said main totalizer, item counters for said main keys, item counters for said by-keys, driving means for said item counters, and operative connections between the main and by-keys with said item counters adapted to move one unit the allotted item counter when one of said keys is depressed.
27. In a machine of the class described, a motor key, locking means therefor, a setting key, normally disengaged connections between said setting key and said locking means, and a special key for engaging said connections, whereby said motor key can be released by said setting key.
28. In a machine of the class described, a motor key, locking means therefor, a set of main keys adapted to set the machine for its primary operations, connections between said main keys and said locking means adapted to release the latter on depression of a main key, a set of secondary keys, disengageable connections between said secondary keys and said locking means, said last-mentioned connections being normally disengaged, and a special key adapted to engage said last-mentioned connections.
29. In a machine of the class described, control totalizers, total keys therefor, by-keys for throwing in said control totalizers, block bars for said by-keys, a block shaft, bows thereon cooperating with said block bars, a rocking lever connected to said total keys and normally disengaged from said bows, but engaged therewith by depressing a total key, a motor key, locking means therefor, and operative connections between said rocking lever and said locking means to free the motor key upon depressing a total key and then a by-key.
30. In a machine of the class described the combination of a main totalizer, a plurality of controlling totalizers, amount keys, operation keys for said main totalizer, total keys for said controlling totalizers, account keys for setting the account number, block bars for said keys, a shaft rotatably mounted in the frame, a spring acting upon said shaft, a bow rigid on said shaft, lugs on said bars for said operation keys normally engaged by said bow by spring action, a second bow cooperating with said block bars for the account keys, an arm on said shaft, an inclined face on said block bar for the total keys, and a second arm on said shaft cooperating with said inclined face, all said members so cooperating as to cause the block bars for said operation keys to be released upon one of the account keys or a total key being depressed.
31. In a machine of the class described the combination of a main totalizer for additions and subtractions and taking totals, operation manipulative means for amounts to be set in first place, operation manipulative means for amounts to be set in second place, account totalizers, by-keys for throwing in said account totalizers, locking means for one kind of said operation manipulative means and normally locking said means, and operative connections between said by-keys and said locking means so constructed that the locking is released by depressing a by-key.
32. In a machine of the class described the combination of a main totalizer for additions and subtractions and taking totals, operating manipulative means for amounts to be set in first place, operation manipulative means for amounts to be set in second place,

- account totalizers, by-keys for throwing in said account totalizers, locking means for one kind of said operation manipulative means and normally locking said means, total keys for said account totalizers, and operative connections between said total keys and said locking means so constructed as to cause said locking to be released by depressing a total-key.
33. In a machine of the class described the combination of a main totalizer for additions and subtractions and taking totals, operation manipulative means for amounts to be set in first place, operation manipulative means for amounts to be set in second place, account totalizers, by-keys for throwing in said account totalizers, locking means for one kind of said operation manipulative means and normally locking said means, connections between said by-keys and said locking means so constructed that the locking is released by depressing a by-key, total keys for said account totalizers, and operative connections between said total keys and said locking means constructed as to cause said locking to be released by depressing a total-key, whereby said locking is released by depressing one of said total or said by-keys.
34. In a machine of the class described the combination of a main totalizer for additions and subtractions and taking totals, operation manipulative means for amounts to be set in first place, operation manipulative means for amounts to be set in second place, account totalizers, by-keys for throwing in said account totalizers, block bars for said operation manipulative means, for said by-keys and for said total keys, a block shaft, a bow thereon cooperating with said block bars for the by-keys, an arm rigid on said shaft and cooperating with said block bar for the total keys, a lever loosely mounted on said shaft, an arm rigid on said shaft against which said lever abuts and locks in this position the block bar for said operation manipulative means of one kind, and a lug on said bow cooperating with said lever, all said members so cooperating that said locking is released by depressing one of said total or by-keys.
35. In a machine of the class described the combination of a main totalizer, controlling totalizers, total keys for said main totalizer, throwing in keys for said controlling totalizers, total keys for said controlling totalizers, a motor key for releasing the operation of the machine, locking means for said motor key, and operative connections between said locking means and said keys so constructed that the release of said motor key is effected by depressing a total key of said main totalizer or by depressing a total key of said controlling totalizers and then a throwing in key.
36. In a machine of the class described the combination of a plurality of totalizers, keys arranged in several rows, block bars in each row of keys, a rocking block bow, arms on said bow so cooperating with said block bars that said bow is moved in both rotative directions, and means for keeping said bow in a determined angular position so as to yield in both rotative directions, said bow being adapted to block certain block bars in each of its rocked positions.
37. In a machine of the class described the combination of a main totalizer for additions and subtractions, operation manipulative means for said main totalizer for a determined kind of additions and subtractions, operation manipulative means for another kind of additions and subtractions, manipulative means for taking totals, means for enforcing a definite setting succession of said operation manipulative means, and account totalizers destined to additively take up the additive and subtractive amounts for the main totalizer to be set in second place.
38. The combination with the parts specified in claim 37 of manipulative means for said account totalizers, locking means for said second-mentioned operation manipulative means, and operative connections between said account totalizer manipulative means and said locking means adapted to release the latter.
39. The combination with the parts specified in claim 37 of manipulative means for said account totalizers, locking means for said second-mentioned operation manipulative means, operative connections between said account totalizer manipulative means and said locking means adapted to release the latter, and means for mutually locking said manipulative means for said account totalizers on the one hand and said first-mentioned operation manipulative means and said manipulative means for taking totals on the other hand.
40. In a machine of the class described the combination of a main totalizer, account totalizers, main keys for setting the operations of said main totalizer comprising keys for amounts to be set first, keys for amounts to be set secondly, total keys; by-keys for setting said account totalizers, block bars cooperating with said keys, a block shaft, a bow rotatable on said shaft, arms on said bow extending to the rear end cooperating by inclined faces with said block bars for said by-keys, and other arms on said bow so cooperating with said block bars for said total keys and for said operation keys to be set first that upon depressing one of the last-named keys said bow is locked by said bar raised and upon depressing one of said by-keys said bow is rotated and locks said first-named keys.
41. In a machine of the class described, a main totalizer adapted for addition and subtraction, account totalizers adapted to take

up amounts additively only, certain of said account totalizers being allotted to additions of the main totalizer and the others to subtractions, manipulative means for setting 5 said main totalizer for addition or subtraction, manipulative means for throwing in said account totalizers, and connections preventing the setting of said main totalizer for additions when a subtraction account 10 totalizer has been thrown in and for preventing the setting of said main totalizer for subtractions when an addition account totalizer has been thrown in.

42. A machine according to claim 41 in 15 which the manipulative means for throwing in said account totalizers comprise three rows of keys, one row being allotted to additions, another to subtractions, and the third being divided into a portion having addition keys 20 and a portion having subtraction keys, in combination with mutual locking means between the two kinds of keys.

43. A machine according to claim 41, in 25 which said manipulative means for throwing in the account totalizers comprise two sets of keys allotted respectively to the addition account totalizers and the subtraction account totalizers, in combination with means for 30 mutually locking each key of one set with all the keys of the other set.

44. In a machine of the class described the combination of a totalizer, two kinds of setting keys each arranged in a row, block bars actuated by said keys, a block shaft, a bow 35 rotatable on said shaft, means for keeping said bow in a determined angular position so as to yield in both rotative directions, arms on said bow, and inclined faces on said arms cooperating with said block bars, said arms of 40 said one kind of keys extending to the rear and said arms of said other kind of keys extending forwardly, said bow being adapted to block certain of said block bars in each of its rocked positions.

45. A machine according to claim 41, in 45 which said manipulative means for throwing in the account totalizers comprise two sets of keys allotted respectively to the addition account totalizers and the subtraction account 50 totalizers, in combination with means for mutually locking each key of one set with all the keys of the other set comprising: a block bar for each set of keys, a pivotally mounted bow, a forwardly directed arm on said bow 55 cooperating with one of said block bars, a rearwardly directed arm cooperating with the other block bar, and means for yieldingly holding said bow in a determined angular position so as to yield in both directions.

46. In a machine according to claim 37, 60 totalizers among said account totalizers destined for taking up said additive amounts, account totalizers destined for taking up said subtractive amounts, manipulative means for 65 said totalizers allotted to additive amounts,

manipulative means for said totalizers allotted to subtractive amounts, and means for locking said additive operation manipulative means by means of said subtractive totalizer manipulative means and for locking said subtractive operation manipulative means by 70 means of said additive totalizer manipulative means.

47. A machine according to claim 41 in which said connections comprise: block bars for the manipulative means for said account totalizers, a pivotally mounted bow, a forwardly directed arm on said bow cooperating with the block bar of the manipulative means for one kind of account totalizers, a rearwardly directed arm on said bow cooperating with the block bar of the manipulative means for the other kind of account totalizers, means for yieldingly holding said bow in a determined angular position so that 80 it can rock in either direction, and a stop connected to said bow and adapted to be moved upon rocking of said bow into the path of the manipulative means for setting the main totalizer for addition or subtraction according to whether the bow is rocked by a subtraction or addition account totalizer manipulative means.

48. In a machine of the class described the combination of a main totalizer, controlling 85 totalizers, operation keys for said main totalizer, a sub-total key among said keys, keys for throwing in said controlling totalizers, total keys for said controlling totalizers, a block bar actuated by said total key, a lug 90 thereon, a block bar actuated by said sub-total key, a slot therein, a block shaft, a bow rotatable on said shaft, an arm on said bow cooperating with said slot, and a second arm cooperating with said lug.

49. In a machine of the class described, a main totalizer, control totalizers, main keys for simultaneously throwing in said main totalizer and certain of said control totalizers for various kinds of operations, keys for 100 selectively throwing in the other control totalizers, interlocking means for preventing more than one of said keys to be depressed at a time, and means for throwing said interlocking means into and out of operation.

50. In a machine of the class described, a main totalizer, control totalizers, main keys for simultaneously throwing in said main totalizer and certain of said control totalizers for various kinds of operations, keys for selectively throwing in the other control totalizers, interlocking means for preventing more than one of said keys to be depressed at a time, a special key for setting 110 the machine for taking totals from said control totalizers, and connections between said special key and said interlocking means whereby the latter is thrown into operation 115 when said special key is depressed and out 120

125

- of operation when said special key is released.
51. In a machine of the class described the combination of setting keys arranged in three rows, a block bar for each of said rows and actuated by said keys, two pivotally mounted bows yielding means for holding said bows in a determined angular position so as to yield in both rotative directions, and arms on said bows so arranged with respect to said block bars that both bows are rocked oppositely to one another by moving the block bar of the first row, clockwise by moving the block bar of the second row, and anti-clockwise by moving the block bar of the third row whereby a mutual blocking is provided between the first row on the one hand and either of the second and third rows on the other hand.
52. In a machine of the class described the combination of a plurality of rows of keys, block bars in said rows, a block shaft, bows rotatable and shiftable on said shaft, arms on said bows cooperating with said bars and adapted to mutually lock said block bars, and means for shifting said bows in order to throw-in and out said mutual locking.
53. In a machine of the class described the combination of a plurality of rows of keys each containing a plurality of keys, mutual lockings between the keys of each row, mutual lockings between certain groups of rows of keys, and mutual lockings between the rows of keys of certain groups.
54. In a machine of the class described the combination of a totalizer, an auxiliary totalizer, main keys for controlling the operations of said main totalizer, a key for throwing in said auxiliary totalizer, means for mutually locking said main keys and said auxiliary totalizer key, and means for releasing said mutual locking.
55. In a machine of the class described the combination of a totalizer, an auxiliary totalizer, main keys for controlling the operations of said main totalizer, a key for throwing in said auxiliary totalizer, block bars actuated by said keys, total keys, means for mutually locking said main keys and said auxiliary totalizer key consisting of a rocking member having two arms cooperating with said block bars and located normally out of the path of said block bars, and operative connections between said rocking member and said total keys enabling said arms to come, upon depressing a total key, into the path of said block bars.
56. In a machine of the class described the combination of a main totalizer and an auxiliary totalizer both destined for additions and subtractions, transaction totalizers, account totalizers, main keys adapted to simultaneously control an operation of said main totalizer and to throw-in a transaction totalizer, an auxiliary totalizer key adapted to throw-in said auxiliary totalizer upon certain amount operations of said main totalizer occurring, by-keys for throwing in said account totalizers and arranged in three rows and allotted to additive or subtractive operations of said main totalizer, a mutual locking between said two kinds of by-keys, mutual locking between the by-keys of one row, mutual locking between said main keys, a differential member in each row of keys, block bars in each row of keys and for the auxiliary totalizer key, a block shaft, two bows rotatable and shiftable on said shaft, total keys for taking totals from said auxiliary totalizer, said account and transaction totalizers, means for shifting said bows upon depressing a total key, a mutual locking between said main keys and said auxiliary totalizer key rendered operative by depressing said total keys, and arms on said bows reaching, upon shifting said bows, the path of said block bars and so arranged that upon depressing a main totalizer key or said auxiliary totalizer key both bows rock oppositely to one another, and upon depressing a by-key of the left-hand or middle row of by-keys both bows rock anti-clockwise and upon depressing a by-key of the right-hand row of by-keys both bows rock clockwise, so that after depressing a total key and a throw-in key all remaining throw-in keys are locked.
57. The combination with the parts specified in claim 1 of a set of account keys, a detent means therefor, releasing means for said detent means and connections whereby said releasing means is thrown out of operation upon depression of one of said first-mentioned setting keys and is thrown into operation again upon depression of one of said total-taking setting keys.
58. The combination with the parts specified in claim 1 of detents for said setting keys, a rocking member for releasing said setting keys actuated at each operation of the machine, a set of account keys, detents therefor, a laterally shiftable rocking frame normally in position to be rocked by said rocking member adapted to release said account keys, yielding means urging said rocking frame toward normal position, means controlled by said first-mentioned setting key for shifting said rocking frame, and a detent controlled by said total-taking setting keys for holding said rocking frame in shifted position.
59. In a machine of the class described the combination of a totalizer, keys for setting the operations of said totalizer, differential actuators controlled by said keys, blind keys arranged beside said keys, means connecting said keys and the corresponding blind keys and adapted to transmit the movement of said keys to their blind keys, and slides cooperating with the connections between said

keys and blind keys and comprising interlocking means for said keys.

60. In a machine of the class described the combination of a totalizer, keys for setting the operations of said totalizer, differential actuators controlled by said keys, blind keys arranged beside said keys, rigid key partitions in the machine, a rocking frame mounted in said partitions, slots in said keys and blind keys, a rocking rod on said frame and engaging said slots, pins on said blind keys, pins on said keys, members actuated by said pins and members actuated by said rocking rod.

61. In a machine of the class described the combination of a totalizer, manipulative means for the amounts and the operations of said totalizer, a driving mechanism, detent means adapted to lock said manipulative means for the time of an operation of the machine and comprising a shaft connected to said driving mechanism, a cam disk on said shaft, connections between said cam disk and said detent means, a motor key destined for releasing the operation of the machine, and connections between said motor key and said cam disk producing a motion locking said manipulative means, of said disk upon the motor key being depressed.

62. In a machine of the class described the combination of a totalizer, manipulative means for the amounts, a driving mechanism, a shaft connected to said driving mechanism, detent means adapted to lock said manipulative means for the time of an operation of the machine comprising a cam disk limitedly rotatably on said shaft, a motor key adapted to release the operation of the machine, a rocking bow engaging said motor key, and a rod pivoted to said bow and so cooperating with said cam disk that this latter has imparted to it a rotation required for locking said manipulative means.

63. In a machine according to claim 62, a notch in said cam disk, a roll on said detent means so arranged as to engage said notch under spring action and to retain said cam disk near the end of the operation of the machine.

64. The combination with the parts specified in claim 62 of manipulative means for the operations of said totalizer, a detent means therefor, a second cam disk connected thereto, and a second rod on said bow for said second cam disk.

65. The combination with the part specified in claim 62 of manipulative means for the operations of said totalizer, a detent means therefor, a second cam disk connected thereto, a second rod on said bow for said second cam disk, account keys for setting account numbers, type carriers connected thereto, detent means for said account keys, and disengagable connections between said detent

means and said detent means for the operation manipulative means.

66. In a machine of the class described the combination of a plurality of totalizers for entering amounts and taking totals, amount keys, operation keys for the different totalizers comprising total keys arranged in different key rows, and connections between said amount keys and said total keys of the different key rows and adapted to effect a mutual locking between said amount keys and all total keys.

67. In a machine of the class described the combination of a plurality of totalizers for entering amounts and taking totals, amount keys, operation keys for the different totalizers comprising total keys arranged in different key rows, block bars actuated by said amount keys, a slot in each block bar, block bars actuated by said total keys, a block shaft, arms rigid thereon engaging said slots and normally extending in the direction of said slots, and second arms rigid on said shaft and cooperating with the block bars of said total keys and so arranged as to turn said shaft upon a total key being depressed and to move said first-named arms over a full portion of said block bars for the amount keys whereby said keys are locked.

68. In a machine of the class described, a totalizer, a total key for positive totals, a total key for negative totals, means for materially embodying the sign of the total contained in said totalizer, means connecting said two keys with said sign embodying means, said connecting means being adapted to release the key corresponding to the total contained in said totalizer and to lock the other of said two keys, and manipulative means for interrupting said connecting means.

69. In a machine of the class described, a totalizer, a total key for positive totals, a total key for negative totals, a block shaft, a block bar for each of said total keys, means for materially embodying the sign of the total contained in said totalizer comprising a notched controlling disk, two feeling members so cooperating with said disk that always one of them is opposite to a notch and the other to a full circumferential portion of said disk, and two bows on said block shaft connecting said block bars to said feeling members.

70. A machine as specified in claim 69 in which said bows are arranged shiftably on said block shaft, in combination with control totalizers, a total key for controlling total operations of said control totalizers, and connections between said bows and said last-named total key adapted to cause said bows to be shifted upon depressing said last-named total key, whereby the arms of said bow will be removed from the path of said block bars.

The foregoing specification signed at Cologne, Germany, this 10th day of September, 1927.

5   ERNST BREITLING.
          WILHELM BRAUER.
          KARL AUGUST LEHMANN.
          MARTHA BORNKESSEL,
          *Administratrix of Bruno Bornkessel,
          Deceased.*
